UNITED STATES PATENT OFFICE.

ARNOLD S. BERTELS, OF TENAFLY, NEW JERSEY, AND EDWIN F. TRAPP, OF VALLEY STREAM, NEW YORK, ASSIGNEES TO WESTERN ELECTRIC COMPANY, INCORPORATED, OF NEW YORK, N. Y., A CORPORATION OF NEW YORK.

AUTOMATIC TESTING SYSTEM FOR AUTOMATIC TELEPHONE SWITCHES.

Application filed December 8, 1923. Serial No. 679,312.

To all whom it may concern:

Be it known that we, ARNOLD S. BERTELS and EDWIN F. TRAPP, citizens of the United States of America, residing at Tenafly, in the county of Bergen and State of New Jersey, and at Valley Stream, in the county of Nassau and State of New York, respectively, have invented certain new and useful Improvements in Automatic Testing Systems for Automatic Telephone Switches, of which the following is a full, clear, concise, and exact description.

This invention relates to telephone exchange systems and more particularly, to a testing device for use in machine switching systems for testing selector switches.

One of the principal requirements in the operation of a telephone exchange system is that of maintaining the central office equipment in proper working condition. In case of a manual exchange, the central office equipment is relatively simple and its apparatus is kept in good condition without much trouble. However, in the case of a mechanical office, its equipment is much more complicated. The establishment of different classes of calls brings into operation various combinations of selector mechanisms of various types. The amount of apparatus used in mechanical exchange systems is very large and much of it is made up of moving parts subject to loss of adjustment while in use. For this reason, apparatus of this nature, such as relays, interrupters, sequence switches, clutches and selector mechanisms, must be carefully watched to detect such loss of adjustment due to wear or broken parts which results from normal use or mistreatment.

Naturally, the failure of any piece of apparatus to function properly will result in the stopping of the progress of calls or in the false routing of calls. Such failures ordinarily would not be detected except where calls are repeatedly reported as incomplete, and such service interruptions, if frequent enough, would assume serious proportions from a service standpoint. It is therefore important that the apparatus of an exchange be regularly tested to determine if it is in suitable condition for rendering efficient service; first, before its

reported failure, and second, after the apparatus has been withdrawn from service for repair or adjustment to determine if such repairs or adjustments place the particular apparatus in serviceable condition. After repair and adjustment, the apparatus should be given vigorous and repeated tests under conditions simulating those under which it will function in actual service before it is again placed in service.

It is, therefore, the object of this invention to provide an improved testing device for applying tests to selector switches of a telephone exchange system.

More particularly, it is the object of this invention to provide a testing device for testing district selectors of the types disclosed in the patents to F. A. Stearn et al., No. 1,395,977, issued November 1, 1921. No. 1,504,261, granted August 12, 1924, to E. H. Mills and No. 1,513,351, granted October 28, 1924, to D. M. Taggart and F. J. Scudder.

While the invention has been disclosed as particularly adapted for testing switches of the panel type, as disclosed in the aforesaid patent and applications, it will however, be apparent from the following description that the invention has a wider utility and that by slight modification it could be adapted for testing other types of selector switches.

A feature of the invention is the provision of means for operating switches employed in the several selection stages of a mechanical switching system in simulation of the manner in which such switches function in actual service and for observing, through the medium of suitable supervisory apparatus, the accuracy with which the switches under test function.

A further feature of the invention relates to the provision of means for operating a selector switch in the establishment of all of the different classes of connections for which such switch is designed.

A further feature of the invention relates to the provision of means for establishing a connection between the testing device and the selector to be tested.

A further feature resides in the method of repeating a test any number of times on the same selector.

A further feature relates to the provision of means for indicating the type of selector about to be selected and for ascertaining the condition in which the selector was found.

6 A further feature is the provision of means for indicating that the subscriber's dialling circuit has been completed.

Further features reside in the provision of means to make a test of the toll charging 10 apparatus, including the collection of a coin and the operation of one or two party message registers, and the means, first, to send a series of impulses into a sender to simulate those of a dial to cause one selection of a talking path, and, second, to send a similar series of impulses to cause a different talking path selection.

Reference may now be had to the accompanying drawings. Figs. 1 to 10 and 16 20 show the arrangement of apparatus which is included in the district selector testing circuit, and Figs. 12, 13, 14 and 15 show some of the types of district selector circuits which may be tested.

25 More in detail, Fig. 1 shows an arrangement of relays and interruptors of well known design for simulating actual service conditions to be met by the district selector circuits under test. A sequence switch for controlling the operation of this apparatus is also shown.

Fig. 2 shows additional relays and interruptors and also a register to record the number of times the test circuit comes to rest on a terminal which is connected to a 35 district selector circuit which has been made busy by the insertion of a plug in the make busy jack. A lamp associated therewith is also shown as a visual signal of such connection.

40 In Fig. 3 is shown a key which may be operated in order to test the district selector circuit for a false operation of its charging relay, and an associated signal. Relays for simulating line conditions of the message rate and coin collect type are also shown. Fig. 3 also shows a key which upon its operation, permits a second cycle of routine tests to be made. An arrangement is also shown 50 with an associated signal for indicating that more than one master switch is off normal at the same time.

Fig. 4 shows two master switches and one group switch, all of the type disclosed in 55 Patent No. 1,472,465 granted Oct. 30, 1923, by O. F. Forsberg and R. M. De Vignier.

Fig. 5 shows three group switches together with their associated apparatus.

60 In Fig. 6 two registers are disclosed, one to record the number of single tests and the other to record the number of complete tests. Class relays operated in accordance with the particular types of district selector circuits connected to the groups are also illustrated 65 in this figure.

Fig. 7 shows a class sequence switch which is arranged to assume a position determined by the class relays in the preceding figure; and also a dial pulse sequence switch which is arranged to simulate the action of a calling dial. The following keys are also shown in this figure; the "start" key, which must be operated to initiate a routine test; a "control advance" key, which may be operated to advance the test circuit out of any position in which it has inadvertently come to rest; the "particular circuit" key, which must be operated in addition to the start key whenever it is desired to make a test on a particular circuit; a "pass busy plug" key, whose operation will cause the group switch to advance to the next terminal upon encountering a district which is busy due to the fact that a make busy plug has been inserted in the make busy jack; a "pass busy 70 test" key, which may be operated when the group switch encounters a district which is busy in regular telephone traffic; a "return-to-normal" key, whose operation causes the test circuit to be returned to its normal position; and a "lamp" key, which controls the illumination of all the lamps used as signals in the test circuit.

Fig. 8 shows a register sequence switch, a register stepping switch and associated 90 relays for controlling the selection of a particular circuit. A stepping switch and associated apparatus which functions in conjunction with the class sequence switch in the preceding figure is also shown.

95 Fig. 9 shows a combined busy and trouble time alarm circuit and Fig. 16 shows an alternate arrangement which may be used when a separate trouble and a separate busy time alarm circuit is desired.

100 Fig. 10 illustrates the arrangement of four groups of keys which are utilized in the selection of a particular circuit.

Fig. 11 with slight modifications is similar to that shown in Fig. 2 of Patent No. 1,395, 110 977, issued November 1, 1921, to F. A. Stearn et al., illustrating a district selector circuit of the type used in connection with single party and flat rate type lines.

115 Figs. 12 and 13 when placed side by side, Fig. 12 at the left of Fig. 13, show the arrangement of a district selector circuit which functions in connection with a two-party message rate type line similar to that disclosed in Figs. 2 and 3 of Patent No. 1,513, 120 351, granted Oct. 28, 1924, by D. M. Taggart and F. J. Scudder.

125 Fig. 14 illustrates the type of district selector circuit which is used in conjunction with a coin collect type line and is similar to Fig. 2 of Patent No. 1,504,261, granted Aug. 12, 1924 to E. H. Mills.

130 Fig. 15 shows connecting conductors between the district selector circuits of Figs. 11, 12, 13 and 14 and senders 910, 1010, and

1110. Senders 910 and 1010 are of the type disclosed in the above mentioned Patent #1,895,977 and sender 1110 is of the type disclosed in the above identified patent of
5 E. H. Mills.

Fig. 17 shows the manner in which the sheets are to be arranged with respect to one another.

It is thought that the invention will best be understood by a detailed description of operation. An operator desiring to make a complete test upon all the district selector circuits to which this circuit has access, depresses a start key 1. Upon the operation of this key, a circuit is closed from grounded battery, winding of the power magnet of sequence switch 200, upper left contact of sequence switch spring 201, conductor 202, outer left armature and back contact of relay 301, conductor 102, armature and back contact of relay 101, conductor 6, contact of start key 1, to ground on the normal contact of key 2. The power magnet of sequence switch 200 is energized in this circuit, moving this sequence switch from position 1 in to position 2. A circuit is also closed from grounded battery, winding of time measure alarm relay 401, conductor 402, brush arm 403 and its associated normal contact, conductors 404 and 18, to ground on the contact of start key 1. Relay 401 is energized in this circuit and begins the measure of time. This feature will be more fully explained hereinafter.

35 The operation of the start key also completes a circuit from grounded battery, upper right contact of sequence switch spring 228, conductor 205, right armature and back contact of relay 302, conductor 303, winding of relay 501, outer left armature and back contact of relay 502, lower contact of interrupter 504, conductor 505, right inner armature and back contact of relay 103, conductor 104, normal contact of key 2, front contact of key 1, normal contact of key 3, conductor 11, to ground through the normal contact of repeat key 12. Relay 501 is energized in this circuit and connects its winding through its armature and front contact in series with the winding of relay 502, to ground over the following circuit: conductor 508, inner left armature and back contact of relay 509, conductor 510, left armature and back contact of relay 358, conductor 304, upper contacts of sequence switch spring 601, to ground. When the spring of interrupter 504 opens its lower contact, relay 502 is energized. When interrupter spring 504 again engages its lower contact, a circuit is completed from grounded battery, right upper contact of sequence switch spring 228, conductor 205, winding of stepping relay 207, conductor 208, outer left armature and front contact of relay 502, to ground through interrupter 504 over the

path previously traced, energizing stepping relay 207. Relay 207 completes a circuit from grounded battery, winding of relay 307, left armature and back contact of relay 305, conductor 211, right armature and front contact of relay 207, to ground through the left upper contact of sequence switch spring 209. Relay 307 energizes. When interrupter spring 504 disengages its lower contact, relay 307 through its inner armature and front contact connects its winding in series with the winding of relay 305 to ground over conductors 312, 105 and 106, normal contact of return-to-normal key 13 to ground, energizing the relay 305. While so interrupter spring 504 is still engaging its lower contact, a circuit is completed from grounded battery, winding of the master stepping magnet 705, conductor 310, outer armature and front contact of relay 307, outer right armature and back contact of relay 305, conductor 703, master switch arm 702 and its associated contact, conductor 215, outer left armature and back contact of relay 213, left armature and front contact of relay 207, upper left contact of sequence switch spring 209 to ground. Magnet 705 is energized in this circuit. When interrupter spring 504 disengages its lower contact as before mentioned, the circuit for relay 207 is broken, causing this relay to be deenergized. The deenergization of relay 207 in turn causes the deenergization of magnet 705 and the brush assembly of the first master switch is stepped to the first terminal in the well known manner. A circuit now extends from grounded battery, resistance element 669, brush arm 602 and its associated first contact (with which it is engaged at this time as will become apparent later), conductor 606, front contact of start key 1, conductor 14, left contact of sequence switch spring 216, conductor 218, inner right armature and back contact of relay 313, conductor 314, brush arm 709 and its associated first off-normal contact, conductors 711 and 712, winding of off-normal relay 713 to ground, energizing relay 713. The energization of the latter relay completes a circuit for off-normal lamp 714, causing its illumination as an indication to the operator that the first master switch is in its off-normal position. This circuit may be traced from grounded battery, lamp 714, outer left armature and front contact of relay 713, conductor 715, to ground through the right contact of lamp key 15 if the latter is operated. Upon the next engagement of interrupter spring 504 with its lower contact, stepping relay 207 is again energized over the path previously traced, completing a circuit from grounded battery, right upper contact of sequence switch spring 228, conductor 205, winding of relay 321, left armature and back contact of relay 317, inner right armature

and front contact of relay 305, conductor 211, right armature and front contact of stepping relay 207, upper left contact of sequence switch spring 209 to ground, energizing relay 321. Relay 207 also closes a path from grounded battery, winding of master stepping magnet 705, conductors 719 and 720, outer left armature and back contact of relay 721, conductors 722 and 723, outer right armature and back contact of relay 335, conductor 724, brush arm 702 and its associated contact, conductor 215, to ground as previously traced on sequence switch spring 209. Relay 321 upon energizing, connects its winding and the winding of relay 317 in series to ground through its left armature and front contact; and upon the disengagement of interrupter 504 with its lower contact, relay 317 is energized. Relay 207 deenergizes, opening the circuit through stepping magnet 705 which releases, moving the brush assembly of the first master switch to the second terminal. The master switch is now set in position to test all the district circuits associated with the first twenty group switches, the first being shown at 726 and the twentieth at 800. Groups 2 to 19 have been omitted for the sake of clearness in the disclosure.

In this position of the master switch, the class sequence switch 50 shown in Fig. 7 is set in position to test for the particular kinds of district to which the test circuit has access. The districts, as has been before noted, may be either the coin collect, flat rate, or message register one or two-party types. The setting of the class switch for single party district selector circuits will be described. When interrupter spring 504 engages its lower contact, stepping relay 207 is energized as previously described and a circuit is completed from grounded battery, winding of class relay 108, conductors 109 and 612, right inner armature and front contact of relay 317, conductors 324 and 211, to ground over the path previously traced. Relay 108 is energized in this circuit. A path is also closed from grounded battery, winding of group switch stepping magnet 726, conductor 725, brush arm 702 and its associated second contact, conductor 215, to ground on sequence switch spring 209 as previously noted. Magnet 726 energizes in this circuit and upon the disengagement of interrupter spring 504 with its lower contact, stepping relay 207 deenergizes and, as a result, stepping magnet 726 deenergizes moving the brush assembly of the first group switch to its first terminal. Relay 108 deenergizes. When interrupter spring 504 next engages its lower contact, stepping relay 207 again energizes, in turn energizing relay 108 and stepping magnet 726.

Relay 108 through its front contacts controls the operation of class relays 119, 121,

123, 116 and 115. These relays are operated in groups as determined by the particular class of districts connected to the group switch associated with the test circuit.

It will be assumed that single-party district selector circuits are connected to the group switch selected for test. In that case, conductor 111 will be connected over conductor 735 to the first terminal in the arc served by brush arm 732 of the group switch. A circuit then extends from grounded battery, brush arm 604 and its associated contact, conductors 118 and 134, winding of relay 123, conductor 133, left inner armature and front contact of class relay 108, conductors 111, and 735, brush arm 732 of the first group switch and its associated contact, conductor 733, brush arm 706 of the first master switch and its associated contact, conductor 513, right armature and back contact of relay 512, conductor 327, outer right armature and back contact of relay 313, conductor 511, inner right armature and back contact of relay 509, conductors 326 and 325, outer right armature and front contact of relay 317, conductors 609 and 16, lower contacts of sequence switch spring 57, conductor 608, to ground through brush arm 603 and its associated contact. Relay 123 is energized in this circuit and completes a circuit from grounded battery, brush arm 604 and its associated contact, conductors 118, 128 and 127, winding of relay 126, conductor 125, outer left armature and front contact of relay 123, conductor 122, outer left armature and back contact of relay 121, conductor 120, outer right armature and back contact of relay 119, to ground. Relay 126 is energized. The energization of relay 126 opens the circuit at its armature and back contact for energizing class switch stepping magnet 615, preventing the motion of this switch.

When interrupter 504 disengages its lower contact, stepping relay 207 deenergizes, in turn causing the deenergization of class relay 108. Relay 123, it will be noted, is locked through its inner left armature and front contact over conductors 105, 106 and 107 to ground at the normal contact of the return-to-normal key 13. The deenergization of relay 207 causes stepping magnet 726 to deenergize, moving the brush assembly of the group switch to its second terminal in the well known manner. A circuit is also established from grounded battery, brush arm 604 and its associated contact, conductors 118 and 128, winding of relay 131, conductor 130, outer right armature and front contact of relay 123, conductors 106 and 107, normal contact of key 13 to ground, energizing relay 131, which locks through its inner left armature and front contact, conductor 132 to ground, as previously mentioned, on the normal contact of key 13. The energization

of relay 131 establishes a circuit extending from grounded battery, winding of the power magnet of sequence switch 50, lower right contact of sequence switch spring 53, conductor 143, inner right armature and front contact of relay 123, conductors 140 and 139, inner right armature and front contact of relay 131 to ground, for moving this sequence switch out of position 1 and 10 into position 8, which is the position assumed by the class switch for testing single-party district selector circuits.

While sequence switch 50 is in motion, a circuit is in existence for energizing relay 509 from grounded battery, winding of relay 509, conductor 514, to ground over the circuit previously traced for sequence switch magnet 50. The energization of relay 509 opens at its outer right armature and back 15 contact an energizing circuit for sequence switch magnet 200, thus preventing this sequence switch from moving out of position 2 until the class switch is properly set. Upon the setting of the class switch, the circuit of relay 509 is broken, allowing this 20 relay to deenergize.

Upon the deenergization of relay 207 due to the action of interrupter spring 504, relay 108 and group switch stepping magnet 30 726 are deenergized, the deenergization of the latter causing the brush assembly of the group switch to step to the second terminal. A circuit also extends from grounded battery, winding of power magnet of sequence 35 switch 200, lower left contact of sequence switch spring 201, conductor 219, left contacts of sequence switch spring 613, conductor 614, outer right armature and front contact of relay 131, conductor 145, outer 40 right armature and back contact of relay 509, conductor 515, right armature and front contact of relay 321, conductor 328, left armature and back contact of relay 207, upper left contact of sequence switch spring 45 209, to ground for advancing this sequence switch out of position 2 and into position 3. Ground on sequence switch spring 210 advances the sequence switch to position 5. As this sequence switch passes through positions 3 and 4, a circuit exists from the 50 ground, lower contacts of sequence switch spring 221, conductor 240, right armature and back contact of relay 213, conductor 241, upper contacts of sequence switch spring 55 57, conductor 20, left armature and back contact of relay 295, conductor 242, winding of class stepping magnet 615 to grounded battery, energizing this magnet. As sequence 60 switch 200 leaves position 4, this circuit is opened, deenergizing magnet 615 and moving the brush assembly of the class stepping switch to the second terminal. The lamp connected to the first terminal associated with brush arm 605 is extinguished, and the 65 lamp associated with the second terminal is

illuminated in a circuit extending from grounded battery, lamp 617, terminal 2, brush arm 605, conductor 670, contact of lamp key 15 (if operated), to ground. It should be noted here that a lamp is connected to each terminal in the arc served by brush arm 605 and the progress of the switch from terminal to terminal may be followed by this means.

The test circuit is now prepared to test the 70 condition of the district selector circuit to which it is connected. If the terminal of the group switch is spare, that is, no district selector circuit is connected thereto, test conductor 739 will be grounded and sleeve conductor 768 will be opened. With sequence switch 200 in position 5, a circuit is closed from grounded battery, winding of the power magnet of sequence switch 200, upper right contact of sequence switch spring 201, conductor 247, outer armature and back contact of relay 516, conductor 517, right outer armature and back contact of relay 518, inner right armature and back contact of relay 520, conductor 251, right upper contact 80 of sequence switch spring 237 to ground, for moving this sequence switch out of position 5 and into position 1. Sequence switch 200 is then advanced out of position 1 into position 2 over a circuit from grounded 85 battery, winding of the power magnet of sequence switch 200, upper left contact of sequence switch spring 201, conductor 202, outer left armature and back contact of relay 301, conductor 102, armature and back contact of relay 101, conductor 6, front contact of start key 1, normal contact of key 2, to ground. When interrupter spring 504 next engages its lower contact, stepping relay 207 energizes in the well known manner, 90 establishing a circuit from grounded battery, winding of group switch stepping magnet 726, conductor 725, brush arm 702 and its associated contact, conductor 215, left outer armature and back contact of relay 213, 95 left armature and front contact of relay 207, upper left contact of sequence switch spring 209 to ground, energizing the magnet. When interrupter spring 504 disengages its lower contact, stepping magnet 726 100 deenergizes, causing the brush assembly of the group switch to move to the third terminal. If this terminal is also a spare one, the above described cycle of operations is 105 repeated and the brush assembly of the group switch is moved to the fourth terminal. If, however, a district selector circuit is connected to the second terminal, the test circuit will make one of the following 110 described tests.

A district selector circuit may be in one of three conditions. It may be in a busy condition due to the fact that a "make-busy" plug has been inserted in the "make-busy" jack of the circuit; it may be busy due to the 115 120 125 130

fact that it is performing its usual function in regular telephone traffic; or it may be in an idle condition.

It will be assumed that the district selector circuit connected to the terminal of the group switch has been made busy by the insertion of a "make-busy" plug in the "make-busy" jack. Test conductor 739 will be connected to ground at the contact of the 10 jack and sleeve conductor 768 will be connected to the battery through the lower right contact of sequence switch spring 901, left contact of relay 903 through the winding of relay 902. As sequence switch 200 advances 15 from position 2 to position 5, a circuit is closed from grounded battery, right winding of relay 902 (Fig. 11), left contact of relay 903, lower right contact of sequence switch spring 901, conductor 768, brush arm 20 732 and its associated second contact, conductor 733, brush arm 706 and its associated contact, conductor 513, right armature and back contact of relay 512, conductor 327, outer right armature and back contact of 25 relay 313, conductor 511, right contact of sequence switch spring 231, conductor 522, winding of relay 521 to ground, causing the energization of relay 521. The energization of this relay completes a circuit from 30 grounded battery, armature and front contact of relay 521, winding of relay 518, conductor 524, right armature and back contact of relay 516, right armature and back contact of relay 526, conductors 527 and 528, 35 upper left contact of sequence switch spring 237 to ground, energizing relay 518. Relay 518 locks to battery on its inner right front contact and armature. The circuit through register 163 at the outer left armature and 40 back contact of relay 518 is open preventing the operation of this register; and the advance circuit for sequence switch 200 through the outer right armature and back contact of relay 518 is also open, preventing the advance of sequence switch 200 out of position 45 5. With sequence switch 200 in position 5, a circuit extends from grounded battery through the winding of register relay 532 and lamp 533 in parallel, conductors 531 and 530, inner left armature and front contact of relay 518, conductor 251, upper right contact of sequence switch spring 237, to ground. Lamp 533 is illuminated and register 532 is operated to record the busy condition of the district selector. Sequence switch 200 will remain in position 5 until the operation of "pass-busy-plug" key 7. The operation and function of this key will be more fully explained hereinafter.

60 It will now be assumed that the district selector circuit connected to the terminals of the group switch is performing its usual function in regular telephone traffic. Under this condition, test conductor 739 and sleeve conductor 768 are connected to ground. As

sequence switch 200 enters position 4 in its advance from position 2 to position 5, a circuit is established from grounded battery, winding of relay 534, outer right armature and back contact of relay 520, conductor 536, left contact of sequence switch spring 231, conductor 511, outer right armature and back contact of relay 313, conductor 327, right armature and back contact of relay 512, conductor 513, brush arm 706 and its associated contact, conductor 733, brush arm 732 and its associated contact, conductor 768 through the cut-off relay in the line switch circuit associated with the district selector circuit to ground, energizing relay 534. A circuit is established from grounded battery, winding of relay 516, conductor 538, to ground through the armature and front contact of relay 534. Relay 516 in energizing, closes an obvious path for relay 541 and at 75 the outer left armature and back contact of relay 516 opens a circuit for advancing sequence switch 200 out of position 5 into position 1. Relay 541 locks on its own inner left armature and front contact, conductor 542, upper contact of sequence switch spring 232, conductor 249, brush arm 710 and its associated contact, conductor 738, brush arm 727 and its associated contact, conductor 739, normal contact of jack 904, conductor 905, 80 inner left armature and front contact of relay 902 to ground. The energization of relay 541 opens a circuit through register 163 at its outer right armature and back contact and also opens a circuit at its outer left armature and back contact through test relay 526, preventing a false operation of this relay. A circuit is also established from grounded battery, "pass-busy" test lamp 22, conductors 21 and 544, right inner armature and front contact of relay 541, conductor 251, upper right contact of sequence switch spring 237 to ground, illuminating the lamp as an indication to the operator that the test circuit is connected to a district selector circuit which is busy in regular traffic. A circuit is also completed from grounded battery, right winding of relay 313, conductor 543, to ground over the path just traced. Relay 313 energizes, causing 100 the deenergization of relay 534. Sequence switch 200 will remain in position 5 until either the district selector circuit becomes idle or "pass-busy-test" key 8 is operated. The function of this key will be more fully described hereinafter.

It will now be supposed that the district selector circuit associated with the second terminal of the group switch is idle. Under this condition, it is obvious from an inspection of Fig. 11 that both test conductor 739 and sleeve conductor 768 are connected to battery. As sequence switch 200 reaches position 4 1/4 in its advance out of position 2 into position 5, a circuit is established from 125

- grounded battery, right contacts of sequence switch spring 906, inner left armature and back contact of relay 902, conductor 905 normal contact of jack 904, test conductor 5 739, brush arms 727 and 710 and their associated contacts, conductor 249, upper contact of sequence switch spring 232, conductor 542, left armature and back contact of relay 512, outer left armature and back contact 10 of relay 541, conductor 546, outer left armature and back contact of relay 552, to ground through the winding of test relay 526. The test relay 526 is energized in this circuit and completes a path from grounded battery, 15 windings of relays 520 and 586 in parallel, conductor 548, right armature and front contact of relay 526, conductors 527 and 528, upper left contact of sequence switch spring 237 to ground, causing the energization of 20 relays 520 and 586. Relay 520 through its inner left armature and front contact, closes a locking path for relays 520 and 586 over conductors 549 and 528 to ground on sequence switch spring 237. A circuit now 25 extends from ground, upper right contact of sequence switch spring 237, conductor 251, winding of relay 582, conductor 246, left contacts of sequence switch spring 236, conductor 551, outer right armature and front 30 contact of relay 520, conductor 536, left contact of sequence switch spring 231, conductor 511, outer right armature and back contact of relay 313, conductor 327, right armature and back contact of relay 512, conductor 513, 35 brush arms 706 and 732 and their associated contacts, conductor 768, lower right contact of sequence switch spring 901, left back contact of relay 903, right winding of district sleeve relay 902, to grounded battery. 40 Relay 582 and district sleeve relay 902 are energized. The latter relay at its inner left armature and front contact replaces the usual battery on the test conductor 739 with ground. The energization of relay 582 45 closes an obvious circuit for relay 552 which in turn closes an obvious circuit for relay 553, and at its outer left armature and back contact opens the energizing circuit of test relay 526. Relay 526 is a slow-to-release relay and with sequence switch 200 in position 5, a circuit is established from ground on test conductor 739, brush arms 727 and 710 and their associated contacts, conductor 249, upper contact of sequence switch spring 232, conductor 542, left armature and back contact of relay 512, outer left armature and back contact of relay 541, conductor 546, outer left armature and front contact of relay 552, conductor 554, left armature and 55 front contact of relay 526, which has not yet released, conductor 555, left winding of relay 252, to battery. Relay 252 energizes and through its right winding, armature and front contact, locks to ground at the lower left contact of sequence switch spring 237. 60 A circuit may now be traced from grounded battery, winding of the power magnet of sequence switch 200, lower right contact of sequence switch spring 201, left armature and front contact of relay 252, to ground 70 on conductor 542, for advancing sequence switch 200 out of position 5 into position 6. Relay 254 is now energized from battery over the dial tone circuit from the sender. This path may be traced from ground, winding 75 of the dial tone induction coil in sender 910, conductor 911, sender selector brush 907 and its associated contact, conductor 908, upper left contact of sequence switch spring 909, conductor 740, brush arms 730 and 707 80 and their associated contacts, conductor 742, outermost right armature and back contact of relay 332, conductor 333, winding of relay 254, upper right contact of sequence switch spring 229, conductor 257, intermediate 85 right armature and back contact of relay 332, conductor 334, brush arms 708 and 729 and their associated contacts, conductor 744, lower left contact of sequence switch spring 917, conductor 918, inner right armature 90 and front contact of relay 919, sender selector brush arm 920 and its associated contact, conductor 912, through the winding of the pulsing relay in sender 910 to battery. A circuit is now in existence for advancing 95 sequence switch 200 from position 6 into position 7 from grounded battery, winding of the power magnet of sequence switch 200, lower left contact of sequence switch spring 235, armature and front contact of relay 254, upper contact of sequence switch spring 232, to ground on conductor 249 as previously described. 100 It may be noted here that with sequence switch 200 in position 6, a circuit extends from grounded battery, winding of relay 335, conductor 336, lower right contact of sequence switch spring 209, to ground. Relay 335 upon energizing, opens at its outer right armature and back contact the circuit 110 through the stepping magnet 705 of the first master switch, preventing the master switch from stepping to the second terminal at the end of a complete cycle. The function of relay 335 will be more fully explained in 115 connection with the selection of the second master switch. 120 Preliminary operations preparatory to making a routine test of the district selector circuit, have now been completed, it being assumed that the district selector circuit has seized an idle sender. The test circuit is now prepared to send three digit impulses in to the sender. 125 With sequence switch 200 in position 7, a circuit is completed from grounded battery, winding of the power magnet of sequence switch 80, upper contact of sequence switch spring 81, right armature and back contact of relay 26, conductor 556, left inner arm- 130

ture and front contact of relay 553, conductor 259, upper contact of sequence switch spring 226, to ground. Sequence switch 80 advances out of position 1 and continues to 5 advance through its twenty positions to normal position 1, due to ground at the lower contact of sequence switch spring 81. A dialing circuit from the sender extends from grounded battery, winding of the pulsing 10 relay in sender 910, conductor 911, sender selector brush arm 907 and its associated contact, conductor 908, upper left contact of sequence switch spring 909, conductor 740, brush arms 730 and 707 and their associated 15 contacts, conductor 742, outermost right armature and back contact of relay 332, conductor 333, lower left contact of sequence switch spring 225, armature and back contact of relay 260, conductor 261, resistance 94, upper contact of sequence switch 20 20 spring 84, conductor 256, left upper contact of sequence switch spring 230, conductor 257, intermediate right armature and back contact of relay 332, conductor 334, brush arms 708 and 729 and their associated contacts, conductor 744, lower left contact of sequence switch spring 917, conductor 918, inner right armature and front contact of relay 919, sender selector brush arm 920 and 25 its associated contact, conductor 912, through the winding of the balancing coil of sender 910, to ground. It will be noted that while sequence switch 80 is making one complete revolution, this dialing circuit will be alternately closed and opened at the contact of sequence switch spring 84. These pulses will simulate the action of the calling dial and will cause registrations to be made in the well known manner in the sender. 30 When sequence switch 80 reaches position 8, that is, after four pulses have been sent, the circuit through the contact of sequence switch spring 84 is shunted over conductor 27, upper contact of sequence switch spring 89, conductor 93, right contact of sequence switch spring 62, conductor 262, upper right contact of sequence switch spring 230, to conductor 257. The dialing circuit is thus 35 closed through and the impulses cease. As sequence switch 80 enters position 14, a circuit is completed from ground, upper contact of sequence switch spring 83, left contact and winding of relay 26 to grounded battery, energizing this relay. Relay 26 forms 40 a locking path for itself through its left armature and front contact, conductor 556, inner left armature and front contact of relay 553, conductor 259, upper contact of sequence switch spring 226, to ground. The 45 function of relay 26 is to prevent sequence switch 80 from making a premature second revolution if sequence switch 200 fails to advance out of position 7. This is accomplished by opening at its right armature and back contact, the energizing circuit of the 50

power magnet of sequence switch 80. As sequence switch 80 advances into position 19½, a circuit is completed for advancing sequence switch 200 out of position 7 and into position 8. This circuit may be traced 70 from grounded battery, winding of the power magnet of sequence switch 200, upper left contact of sequence switch spring 233, conductor 95, lower contact of sequence switch spring 82, to ground. As sequence switch 75 200 leaves position 7, the holding circuit for relay 26 is broken at sequence switch spring 226 and this relay releases.

In position 8 of sequence switch 200, a circuit is completed for causing sequence 80 switch 80 to make a second revolution in order to simulate the pulses of a second digit. This circuit extends from grounded battery, winding of the power magnet of sequence switch 80, upper contact of sequence switch spring 81, right armature and back contact of relay 26, conductor 556, left inner armature and front contact of relay 553, conductor 259, upper contact of sequence switch spring 226, to ground. Sequence 90 switch 80 advances out of position 1 over this circuit and continues its advance through a complete revolution due to the presence of ground at the lower contact of sequence switch spring 81. The dialling circuit extending to the sender is again interrupted at the contact of sequence switch 95 84 until sequence switch 80 reaches position 9½ that is, after five impulses have been sent, and the circuit is shunted over conductor 27, upper contact of sequence switch spring 87, conductor 90, left contact of sequence switch spring 61, conductor 263, lower contact of sequence switch spring 230, to conductor 257. As sequence switch 80 continues its revolution and enters position 14, relay 26 reenergizes as above described and performs its usual function, that is, it prevents a second revolution of sequence switch 80 until after sequence switch 200 advances out of position 100 8. In position 18 of sequence switch 80, a circuit is in existence for advancing sequence 105 switch 200 out of position 8 into position 9 from grounded battery, winding of the power magnet of sequence switch 200, lower right contact of sequence switch spring 233, conductor 96, upper contact of sequence switch spring 82 to ground. As sequence switch 200 leaves position 8, relay 26 releases and a circuit through the power magnet of sequence switch 80 to ground at sequence switch spring 226 is completed to cause sequence switch 80 to make a third revolution. 110

In the course of this third revolution, the impulses constituting the third digit are sent to the sender circuit over the fundamental circuit previously traced through the contact of sequence switch spring 84. The 115 dialling circuit continues to be interrupted 120

until sequence switch 80 reaches position 10½, that is, after six impulses have been sent, at which time it is shunted over conductor 27, lower contact of sequence switch 5 spring 87, conductor 28, upper contact of sequence switch spring 68, conductor 29, left upper contact of sequence switch spring 229, to conductor 257. As sequence switch 80 enters position 14, relay 26 reenergizes 10 a third time to perform its usual function. In position 16½ of sequence switch 80, a circuit is established from grounded battery, winding of power magnet of sequence switch 200, upper right contact of sequence switch spring 233, conductor 97, lower contact of sequence switch spring 83 to ground, advancing sequence switch 200 out of position 15 9 and into position 10.

While the circuit has been described for 20 registering a three-digit number, it should be noted that two and one-digit numbers may also be registered. In the case of a two-digit number, only two revolutions of sequence switch 80 are necessary, while in 25 the case of a one digit number, only one revolution is necessary.

When the registers in the sender circuit are set, the sender advances in the well known manner, causing the district selector 30 circuit to make brush and group selection. It will be noted that the three digits transmitted to the sender by the test circuit are 4, 5 and 6. It is seen that the district selector is driven to the uppermost bank of the 35 frame and the brushes rest on the terminals of the test line as shown in Fig. 11 and which re-enter the automatic test circuit.

A circuit extends from grounded battery, winding of relay 264, conductor 265, upper 40 right contact of sequence switch spring 209 to ground, energizing relay 264. For purposes of test, the terminals of the test circuit on the district frame are the third in the group, the first and second terminals 45 being connected to the front contacts of relay 264. They are thus grounded by the energization of relay 264 and the district selector circuit is caused to hunt in the well known manner to the third terminal, and 50 sequence switch 900 advances to position 10.

When the district selector circuit comes to rest on the terminals of the test circuit, a circuit is completed from grounded battery, winding of relay 266, conductor 267, lower 55 right contact of sequence switch spring 220, conductor 921, terminal 926 and brush 929, conductor 932, upper right and lower left contacts of sequence switch spring 933, conductor 934, outer right armature and front 60 contact of relay 919, sender selector brush arm 935 and its associated contact, conductor 914, through the winding of the stepping relay in sender 910, conductor 916, sender selector brush 938 and its associated 65 contact, conductor 937, lower left and upper

right contacts of sequence switch spring 939, brush 930 and its associated contact 927, conductor 922, lower left contact of sequence switch spring 221, to ground. Relay 266 is energized, completing an obvious circuit 70 for relay 269. Relay 269, through its right armature and front contact, connects its winding in series with the winding of relay 268 to ground at the upper right contact of sequence switch spring 209. Upon 75 the deenergization of relay 266, relay 268 energizes in series with relay 269, which is held energized. Relay 266 deenergizes upon the opening of the circuit just traced due to the advance of the sender circuit. The 80 energization of relay 268 places ground through its left armature and front contact, conductor 270, lower right contact of sequence switch spring 222 to the sleeve terminal of the district multiple, causing the 85 test line circuit to test busy to other hunting district selectors. As the sender advances, performing its usual functions, relay 266 again energizes and a circuit is established from grounded battery, winding of 90 the power magnet of sequence switch 200, lower left contact of sequence switch spring 233, conductor 271, right armature and front contact of relay 268, armature and front contact of relay 266 to ground, for advancing sequence switch 200 out of position 10 and into position 11. It will be noted here that when sequence switch 200 enters position 10½, ground on the sleeve terminal of the district selector is supplied at the right 95 upper contact of sequence switch spring 222 to cause the test circuit to test busy to other hunting district selectors. 100

With sequence switch 200 in position 10, and sequence switch 900 in position 11, a 105 circuit is established for testing the operation of the district supervisory relay 940 by supplying a saturating current thereto. This circuit may be traced from grounded battery, lower left winding of the district 110 repeating coil 941, winding of district supervisory relay 940, upper right contact of sequence switch spring 917, conductor 744, brush arms 729 and 708 and their associated contacts, conductor 334, intermediate 115 armature and back contact of relay 332, conductor 257, left upper contact of sequence switch spring 229, conductor 29, contact of sequence switch spring 223, intermediate 120 armature and back contact of relay 255, right armature and back contact of relay 293, resistance 272, conductor 273, left upper contact of sequence switch spring 225, conductor 333, outermost right armature and back contact of relay 332, conductor 742, brush arms 707 and 730 and their associated contacts, conductor 740, lower 125 right contact of sequence switch spring 909, to ground through the upper left winding of the district repeating coil 941. 130

Sequence switch 900 of the district selector circuit is advanced out of position 11 and into position 14 to await the action of the test circuit in a manner similar to that described in detail in Patent #1,395,977 hereinbefore mentioned, under the control of the registrations set up in the sender as above explained.

With sequence switch 200 in position 11 and sequence switch 900 in position 14, a circuit is established from grounded battery, resistance 274, winding of relay 275, outer armature and back contact of relay 276, inner left armature and back contact of relay 244, conductor 243, upper contact of sequence switch spring 221, conductor 922, terminal 927, brush 930, upper contacts of sequence switch spring 939, lowermost right winding of the district repeating coil 941, lower left contact of sequence switch spring 942, winding of polarized relay 943, upper contacts of sequence switch spring 944, uppermost right winding of repeating coil 941, upper contacts of sequence switch spring 933, conductor 932, brush 929, terminal 926, conductor 921, lower left contact of sequence switch spring 220, resistance 204, to ground. The polarized supervisory relay 943 in the district and relay 275 are energized in this circuit. The energization of the polarized supervisory relay 943 causes the district circuit to advance to position 15. A circuit is completed from grounded battery, right winding of relay 951, lower contact of sequence switch spring 952, armature and front contact of relay 943, upper left contact of sequence switch spring 953 to ground. Relay 951 energizes and establishes a circuit from grounded battery, winding of the power magnet of sequence switch 900, upper left contact of sequence switch spring 954, inner right armature and front contact of relay 951, upper right contact of sequence switch spring 955 to ground for rotating this sequence switch out of position 14 and into position 15.

As sequence switch 900 leaves position 14½ relay 943 releases but relay 951 is held energized over a locking circuit maintaining the sequence switch in position 15. This holding circuit may be traced from grounded battery through the left winding, armature and front contact of relay 951, upper left and lower right contacts of sequence switch spring 956, brush 931, terminal 928, conductor 923 to ground at the upper right contact of sequence switch spring 222.

A circuit is also in existence in position 11 of sequence switch 200 from grounded battery, upper left contact of sequence switch spring 228, winding of relay 276, conductor 277, left upper contact of sequence switch spring 54, to ground, causing the energization of relay 276. Relay 276 completes a circuit from grounded battery, in-

ner armature and front contact of relay 276, conductor 278, winding and left back contact of relay 497, conductor 580, upper contact of interrupter spring 558, conductor 557, right upper contact of sequence switch spring 64, to ground. Relay 497 is energized in this circuit and locks itself through its left armature and front contact, conductor 281, innermost armature and back contact of relay 255 to ground. When interrupter spring 558 engages its lower contact, a circuit is established from ground, upper right contact of sequence switch spring 64, conductor 557, interrupter spring 558 and its lower contact, conductor 284, outer right armature and front contact of relay 497, winding of relay 282, inner armature and front contact of relay 276 to grounded battery, energizing relay 282. Relay 282 locks to ground on its left armature and front contact. When interrupter spring 558 next engages its upper contact, a circuit is completed from ground on interrupter spring 558, conductor 580, right inner armature and front contact of relay 497, right armature and front contact of relay 282, conductor 285, right upper contact of sequence switch spring 235, winding of the power magnet of sequence switch 200 to grounded battery, advancing this sequence switch out of position 11 and into position 12. Ground on sequence switch spring 210 carries sequence switch 200 into position 13. As sequence switch 200 leaves position 11, the holding circuit for relay 276 is broken. This relay deenergizes, in turn causing the deenergization of relays 497 and 282.

As sequence switch 200 leaves position 12, the circuit through relay 275 is opened at the lower contact of sequence switch spring 220, causing relay 275 to deenergize.

When sequence switch 200 enters position 13 relay 275 is reenergized from grounded battery, lower left contact of sequence switch spring 228, conductor 286, winding of relay 275, outer armature and back contact of relay 276, inner left armature and back contact of relay 244, conductor 243, upper contact of sequence switch spring 221, conductor 922, terminal 927, brush 930, conductor 945, upper left contact of sequence switch spring 917, conductor 744, brush arms 729 and 708 and their associated contacts, conductor 334, intermediate right armature and back contact of relay 332, conductor 257, left upper contact of sequence switch spring 229, conductor 29, upper contact of sequence switch spring 223, intermediate armature and back contact of relay 255, right armature and back contact of relay 293, resistance 272, lower right and upper left contacts of sequence switch spring 224, conductor 287, lower contact of sequence switch spring 56, to ground, as an indication that the circuit over the ring

side of the district is completed. A circuit now extends from grounded battery, winding of relay 255, left contact of sequence switch spring 227, armature and front contact of relay 275, upper contact of sequence switch spring 224, to ground over the path just described. Relay 255 is energized and completes a circuit from grounded battery, lower left contact of sequence switch spring 228, conductor 286, outermost armature and front contact of relay 255, conductor 146, lower contacts of sequence switch spring 55, conductor 278, winding and back contact of relay 497, conductor 580, upper contact of interrupter spring 558, conductor 557, upper right contact of sequence switch spring 64, to ground, for energizing relay 497. The energization of relay 255 opens a shunt circuit around resistance 288 and relay 248 at its intermediate armature and back contact, allowing relay 248 to energize and causing the deenergization of the district supervisory relay, 940, as a result of the decrease of current in the circuit due to the inclusion of addition resistance. Relay 275, however, still receives sufficient current to maintain it in its energized condition. Relay 497, upon energizing, locks through its left armature and front contact, conductor 281, inner armature and front contact of relay 255, upper contact of sequence switch spring 220, conductor 921, terminal 926, brush 929, conductors 932 and 946, upper right contact of sequence switch spring 909, conductor 740, brush arms 707 and 730 and their associated contacts, conductor 742, outermost right armature and back contact of relay 332, conductor 333, upper contact of sequence switch spring 225, conductor 273, lower right and upper left contacts of sequence switch spring 224, conductor 287, lower contact of sequence switch spring 56, to ground as an indication that the circuit over the tip side of the district is completed. A circuit is also completed from grounded battery, lower left contact of sequence switch spring 228, conductor 286, outermost armature and front contact of relay 255, conductor 146, lower contacts of sequence switch spring 55, conductor 278, winding of relay 282, outer right armature and front contact of relay 497, conductor 284, lower contact of interrupter spring 558, conductor 557, upper right contact of sequence switch spring 64 to ground, energizing relay 282 which locks to ground at its left armature and front contact.

Upon the release of the district supervisory relay 940, this circuit does not restore to normal since it is held busy by ground to conductor 923 at sequence switch spring 222. The energization of relay 248, as above noted, establishes a circuit from grounded battery, winding of relay 560,

conductors 561, 562 and 289, armature and front contact of relay 248, conductor 147, left upper contact of sequence switch spring 64 to ground, energizing relay 560.

When interrupter spring 558 engages its upper contact, a circuit extends from grounded battery, winding of the power magnet of sequence switch 200, right upper contact of sequence switch spring 235, conductor 285, right armature and front contact of relay 282, inner right armature and front contact of relay 497, conductor 580, upper contact of interrupter spring 558, conductor 557, right upper contact of sequence switch spring 64 to ground, for advancing this sequence switch out of position 13 and into position 14. As sequence switch 200 leaves position 13, ground at sequence switch spring 222 is temporarily removed from conductor 923, releasing the district relay 951 which causes sequence switch 900 to advance to its overflow position 16, in the well known manner.

If the district selector circuit under test fails to advance to its "talking-to-operator" position 15, the indication is given to the test operator in the following manner: Relay 275 will deenergize in position 12 of sequence switch 200. The energizing circuit of relay 255 is thus opened at the front contact of relay 275 and relay 248 fails to energize since relay 255 does not remove the shunt around its winding. The failure of relay 248 to energize, prevents the energization of relay 282. The test circuit is thus held in position 12 until the operation of the time measure alarm circuit.

Assuming that the test of the district selector is successful up to this point, sequence switch 200 leaves position 13. Relays 275 and 255 deenergize, their holding circuits having been broken at sequence switch springs 221 and 227, respectively. When the intermediate armature of relay 255 engages its back contact, a shunt circuit around resistance 288 and relay 248 is established and this relay deenergizes, in turn deenergizing relay 560. With sequence switch 200 in position 14, a circuit for supplying saturating current to the supervisory relay in the district is reestablished. This circuit may be traced from grounded battery, lower left winding of district repeating coil 941 and supervisory relay 940, upper right contact of sequence switch spring 917, conductor 744, brush arms 729 and 708, and their associated contacts conductor 334, intermediate armature and back contact of relay 332, conductor 257, upper left contact of sequence switch spring 229, conductor 29, contact of sequence switch spring 223, intermediate armature and back contact of relay 255, right armature and back contact of relay 293, resistance 272, conductor 273, upper contact of sequence switch spring 225, conductor 333,

outermost right armature and back contact of relay 332, conductor 742, brush arms 707 and 730, and their associated contacts, conductor 740, lower right contact of sequence 5 switch spring 909 upper left winding of district repeating coil 941, to ground. A circuit is also completed in position 14 of sequence switch 200 from grounded battery, contact of interrupter spring 290, winding 10 of relay 291, conductor 559, right contact of sequence switch spring 63, conductors 279 and 280, lower right contact of sequence switch spring 237 to ground, energizing relay 291 which locks to battery through its 15 inner left armature and front contact. Relay 291 connects battery to its outer left armature and front contact to the windings of relays 497 and 282 to ground through the upper and lower contacts, respectively, of 20 interrupter spring 558.

When interrupter spring 558 next engages its upper contact, a circuit is completed from grounded battery, winding of the power magnet of sequence switch 200, upper 25 left contact of sequence switch spring 235, right armature and front contact of relays 291 and 282, inner right armature and front contact of relay 497, conductor 580, upper contact of interrupter spring 558, to ground 30 over the path described. Sequence switch 200 is advanced out of position 14 and into position 15 over this circuit. In position 15, the shunt circuit around resistance 288 and relay 248 is opened at the contact of sequence switch spring 223, causing the release of the supervisory relay of the district and energizing relay 248 as previously described. The energization of relay 248 again causes the energization of relay 560, 40 which in turn completes a circuit from grounded battery, right armature and front contact of relay 560, winding of relay 564, conductor 565, lower left and upper right contacts of sequence switch spring 222 to ground, energizing relay 564 which locks to grounded battery at its left armature and front contact. The release of supervisory relay 940 in the district causes that circuit to restore to normal in the well known manner, opening the circuit through relay 248 which deenergizes. Relay 560, as a result, deenergizes and a circuit is completed from grounded battery, winding of the power magnet of sequence switch 200, upper 45 contact of sequence switch spring 234, conductor 566, right armature and front contact of relay 564, left armature and back contact of relay 560 to ground, advancing sequence switch 200 out of position 15 and, because of the presence of ground at sequence switch spring 210, into position 18.

As sequence switch 200 reaches position 18, a circuit is established from grounded battery, winding of the power magnet of sequence switch 200, lower left contact of se-

quence switch spring 234, conductor 31, upper left contact of sequence switch spring 56 to ground, advancing this sequence switch out of position 18 and into position 1. As sequence switch 200 enters position 18 1/4, a 70 circuit is completed from grounded battery, winding of relay 148, conductor 33, operated contact of start key 1, normal contact of control advance key 2, conductors 569 and 567, right contact of sequence switch spring 75 239 to ground, energizing relay 148 which locks to the same ground at its left inner armature and front contact. The energization of relay 148 completes the following circuits:

The first extends from grounded battery, winding of the power magnet of sequence switch 50, lower left contact of sequence switch spring 53, conductor 150, left armature and back contact of relay 149, inner right armature and front contact of relay 148 to ground, for advancing this sequence switch out of position 8 and into position 9. Relay 401 is held energized, while sequence switch 200 is advancing out of position 18 into position 1, over the second circuit extending from grounded battery, winding and left inner armature and front contact of relay 401, normal contact of time alarm key 416, conductors 405 and 34, normal contact of return-to-normal key 13, conductor 152, outer right back contact of relay 103, conductor 151, outer left armature and front contact of relay 148, conductor 277, upper left contact of sequence switch spring 54, to ground. A third circuit extends from grounded battery, outer right armature and front contact of relay 148, winding of relay 101, conductor 169, lower contact of sequence switch spring 232, conductor 249, brush arms 710 and 727 and their associated contacts, conductor 739, to ground on the district sleeve conductor at the inner left armature and front contact of relay 902. While sequence switch 50 is moving out of position 8 into position 9, relay 509 operates in parallel with the power magnet, performing its usual function and preventing the energization of relay 103 until after the class sequence switch is set. As sequence switch 200 leaves position 18, the holding circuit through relay 520 is opened at the contact of sequence switch spring 237, causing this relay to release.

With sequence switch 200 in position 1 and sequence switch 50 in position 9, a circuit extends from grounded battery, winding of relay 103, conductor 153, upper contacts of sequence switch spring 55, conductor 35, outer left armature and back contact of relay 509, conductor 571, lower contact of sequence switch spring 239 to ground, energizing this relay which locks through its inner left armature and front contact over conductor 164, to ground through the upper 120 125 130

right contact of sequence switch spring 54. As sequence switch 50 reaches position 9, a circuit is also established from grounded battery, winding of relay 283, conductor 177, upper left and lower right contacts of sequence switch spring 65 to ground, energizing this relay.

The test of the district selector circuit with its repeating coil connected in the circuit, will now be described. As the district selector circuit is restored to normal as previously stated, the ground which was on test conductor 739 is removed, causing the deenergization of relay 101. A circuit is then established from grounded battery, winding of the power magnet of sequence switch 200, upper left contact of sequence switch spring 201, conductor 202, outer left armature and back contact of relay 301, conductor 102, armature and back contact of relay 101, conductor 6, front contact of start key 1, to ground on the normal contact of control advance key 2 for advancing this sequence switch out of position 1 and into position 2. In position 2, a circuit is closed through the power magnet of the sequence switch, lower left contact of sequence switch spring 201, conductor 219, left contacts of sequence switch spring 613, conductor 614, outer right armature and front contact of relay 131, conductor 145, outer right armature and back contact of relay 509, conductors 515 and 36, lower right contact of sequence switch spring 59 to ground, moving the sequence switch out of position 2. Ground on sequence switch spring 210 carries it to position 5. As sequence switch 200 advances through positions 3 to 5, the district selector circuit is re-tested for a busy condition as described for the first revolution of the test switch. Should the polarized supervisory relay 943 in the district circuit under test fail to release, the district sequence switch continues to revolve, causing the operation of relays 521 and 518 as previously described. Relay 518, upon energizing, completes a circuit from grounded battery, outer right armature and front contact of relay 283, conductor 573, winding of relay 512, conductor 530, left inner armature and front contact of relay 518, conductor 251, upper right contact of sequence switch spring 237 to ground. The energization of relay 512 opens at its armatures and back contacts the sleeve and test conductors, preventing the operation of relays 520 and 526. Sequence switch 200 will remain in position 5 until the trouble is remedied.

If the district selector circuit under test is found to be idle, relay 254 operates when sequence switch 200 is advanced to position 6, as described for the first revolution of the sequence switch 200. In position 6, the same operations occur as occurred in the same position on the first revolution, and

sequence switch 200 is advanced into position 7 as there described.

With sequence switch 200 in position 7, a circuit is completed from grounded battery, winding of the power magnet of sequence switch 80, upper contact of sequence switch spring 81, right armature and back contact of relay 26, conductor 556, left inner armature and front contact of relay 553, which, it will be remembered, is now energized, conductor 259, upper contact of sequence switch spring 226, to ground. Sequence switch 80 advances out of position 1 and continues to advance through its twenty positions to its normal position 1 due to the presence of ground at the lower contact of sequence switch spring 81. A dialing circuit from the sender extends from grounded battery, winding of the pulsing relay in sender 910, conductor 911, sender selector brush arm 907 and its associated contact, conductor 908, upper left contact of sequence switch spring 909, conductor 740, brush arms 730 and 707 and their associated contacts, conductor 742, outermost right armature and back contact of relay 332, conductor 333, lower left contact of sequence switch spring 225, armature and back contact of relay 260, conductor 261, resistance 94, upper contact of sequence switch spring 84, conductor 256, left upper contact of sequence switch spring 230, conductor 257, intermediate right armature and back contact of relay 332, conductor 334, brush arms 708 and 729 and their associated contacts, conductor 744, lower left contact of sequence switch spring 917, conductor 918, inner right armature and front contact of relay 919, sender selector brush arm 920 and its associated contact, conductor 912, through the winding of the balancing coil of sender 910 to ground.

As previously explained, this circuit is interrupted at sequence switch spring 84. When sequence switch 80 reaches position 4½, that is, after one pulse has been sent, the circuit through the contact of sequence switch spring 84 is shunted over conductor 27, lower contact of sequence switch spring 88, conductor 92, upper left contact of sequence switch spring 62, conductor 262, upper right contact of sequence switch spring 230, to conductor 257. The dialing circuit remains closed for the rest of the revolution of sequence switch 80. In position 14 of this switch, relay 26 energizes and locks, performing its function as before explained. In position 19½, sequence switch 200 is advanced out of position 7 and into position 8 for sending the second digit.

In position 8 of sequence switch 200, the circuit is again closed for starting a second revolution of sequence switch 80. Interruptions are again caused at sequence switch spring 84 until sequence switch 80 reaches

position 5½, that is, after two pulses have been sent, when the contact is shunted over conductor 27, upper left contact of sequence switch spring 88, conductor 91, upper right contact of sequence switch spring 61, conductor 293, lower left contact of sequence switch spring 230, to conductor 257.

In position 18 of sequence switch 80, sequence switch 200 advances out of position 8 into position 9. Sequence switch 80 is then caused to make a third revolution as before described. After three impulses have been sent and sequence switch 80 reaches position 6¾, the dialing circuit is shunted at conductor 27, lower left contact of sequence switch spring 89, conductor 30, lower left contact of sequence switch spring 68, conductor 29, upper left contact of sequence switch spring 229, to conductor 257. Sequence switch 200 is then advanced to position 10 as before.

It will be noted that the digits sent into the sender for registration are 1, 2 and 3. The cross connections between the sender registers and the sender translator are such that the sender class sequence switch will be set in such a position that causes the district to advance into talking position 12, which is a position in which the district repeating coil is included in the talking circuit. The cross-connections at the translator are also such that the district selector elevator is driven as before to the uppermost bank of the frame and the brushes are brought to rest after trunk hunting, as before described, on terminals 926, 927 and 928 which are connected to the test circuit by conductors 921, 922 and 923. The method of cross-connecting is fully explained in Patent No. 1,395,977 to F. A. Stearn et al., issued November 1, 1921.

The operations attendant upon the advance of sequence switch 200 from position 10 to position 13 and sequence switch 900 from position 10 to position 11, are now exactly the same as those previously described for the first revolution of the sequence switches. It will therefore be assumed that sequence switch 200 has reached position 14 and sequence switch 900 has reached position 11. The district selector will then come to rest in position 12 instead of position 14 as mentioned above.

As sequence switch 200 enters position 14, a circuit is established from grounded battery, winding of relay 293, right armature and back contact of relay 294, contact of interrupter spring 292, conductor 154, left contact of sequence switch spring 63, conductors 279 and 280, lower right contact of sequence switch spring 237 to ground energizing relay 293 which locks through the winding of relay 294 and its own left armature and front contact when interrupter spring 292 disengages its contact. Re-

lay 293 opens at its right armature and back contact the circuit supplying saturating current to the district supervisory relay 940 and relay 294 opens the shunt circuit extending around resistance 288 and relay 248. Current through supervisory relay 940 in the district is thus reduced to a value insufficient to hold it energized and it should thereupon release. Relay 294 at its left armature and front contact, reestablishes a circuit through resistances 288, relay 248 and supervisory relay 940 in the district, causing relay 940 to reenergize. The district supervisory relay through whose contact relay 903 is held energized, does not remain deenergized long enough to permit relay 903 to deenergize, due to the fact that this relay is of the slow-to-release type. The district circuit is therefore not returned to normal since supervisory relay 940 is reenergized within a very short interval. When interrupter spring 574 engages its contact, a circuit is completed from grounded battery, winding of the power magnet of sequence switch 200, upper left contact of sequence switch spring 235, right armature and front contacts of relays 291, 282 and 497, conductor 580, left and right armatures and back contacts of relay 576, contact of interrupter spring 574, conductor 37, lower contact of sequence switch spring 64 to ground, advancing this sequence switch out of position 14 and into position 15. Sequence switch 200 continues to revolve out of position 15 over a circuit which may be traced from grounded battery, winding of the power magnet of sequence switch 200, lower right contact of sequence switch spring 234, conductors 156 and 158, upper left contact of sequence switch spring 59, to ground. Sequence switch 200 continues to advance to position 18 through sequence switch spring 210.

In position 18 of the second revolution of sequence switch 200, circuits are completed for registration on message register districts. When sequence switch 900 is advanced to position 17 in the well known manner, relays 345 and 346 are energized in a circuit which may be traced from grounded battery, through the windings of relay 902 in parallel, armature and front contact of relay 947, lower left contact of sequence switch spring 901, conductor 768, brush arms 732 and 706, conductor 513, right armature and back contact of relay 512, conductor 327, outer right armature and back contact of relay 313, conductor 511 left contact of sequence switch spring 231, conductor 536, outer right armature and front contact of relay 520, conductor 551, upper left and lower right contacts of sequence switch spring 238, conductor 330, windings of relays 346 and 345, conductor 347, outer left armature and back contact of relay 157,

conductor 155, lower contact of sequence switch spring 54, to ground. Relay 346, upon energizing, establishes a circuit from grounded battery, winding of relay 560, conductors 561 and 562, inner right armature and back contact of relay 244, conductor 298, left armature and back contact of relay 578, conductor 587, armature and front contact of relay 346, to ground on conductor 347 as previously described. The energization of relay 560 causes, in turn, the energization of relay 564 and the advance of sequence switch 200 out of position 18 into position 1 in the manner hereinbefore described.

15 It should be noted here that in position 17 of sequence switch 200, a circuit is established from grounded battery, upper right contact of sequence switch spring 203, conductor 590, outer right armature and back contact of relay 541, conductor 591, inner left armature and front contact of relay 552, conductor 592, outer left armature and back contact of relay 518, conductor 593, normal contact of repeat key 12, conductor 594, winding of single test register 163, conductor 173, outer right armature and back contact of relay 115, conductor 158, upper left contact of sequence switch spring 59 to ground, energizing the single test register to record the number of single tests made. A circuit also exists from battery as above traced at the outer left armature and back contact of relay 518, thence over conductor 174, winding of complete test register magnet 162 conductor 173, to ground over the path already described. Complete test register 162 operates to record the number of complete tests.

20 It will be noted that a sequence switch 200 entered position 1 on its second revolution, a circuit was established from grounded battery, winding of relay 103, conductor 153, upper contacts of sequence switch spring 55, conductor 35, left outer armature and back contact of relay 509, conductor 571, lower contact of sequence switch spring 239, to ground. Relay 103 energizes and locks through its inner left armature and front contact, conductor 164, right upper contact of sequence switch spring 54, to ground.

25 It will be remembered in describing the restoration of sequence switch 200 upon its first revolution, that it was advanced out of position 18 over a circuit extending from grounded battery, winding of the power magnet of sequence switch 200, lower right contact of sequence switch spring 235, conductor 566, right armature and front contact of relay 564, left armature and back contact of relay 560, to ground. As sequence switch 200 leaves position 18 the circuit through the single test register 163 and complete test register 162 is opened at the contact of sequence switch spring 203, de-

energizing the registers. As sequence switch 200 enters position 18½, a circuit is closed from grounded battery, lower contact of sequence switch spring 203, conductor 155, outer left armature and front contact of relay 103, conductor 166, left armature and back contact of relay 115, conductor 167, winding of relay 161, to ground. Relay 161, upon energizing, locks through its inner right armature and front contact, conductor 175, upper contact of sequence switch spring 58, to grounded battery. Relay 161 also completes an obvious circuit for relay 149 which energizes and locks through its own right armature and front contact to ground at the inner right armature and front contact of relay 148. The class sequence switch 50 is now advanced into position 1 over a path which may be traced from grounded battery, winding of the power magnet of sequence switch 50, right upper contact of sequence switch spring 53, conductor 39, right inner armature and front contact of relay 161, to ground. When sequence switch 50 reaches position 1, it immediately advances to position 8, according to the setting of the class relays as previously described. Relay 161 on energizing, also opens the holding circuit of relay 401 at its inner right armature and back contact, de-energizing this relay.

25 When the sequence switch of the district selector circuit just tested returns to its normal position in the usual manner, ground on the test conductor 739 is removed by the de-energization of relay 902, causing the de-energization of relay 101. A circuit now extends from grounded battery, winding of the power magnet of sequence switch 200, upper left contact of sequence switch spring 201, conductor 202, outer left armature and back contact of relay 301, conductor 102, armature and back contact of relay 101, conductor 6, contact of start key 1 in its operated position, normal contact of control advance key 2, to ground for moving this sequence switch out of position 1 into position 2. As sequence switch 200 leaves position 1, the holding circuit for relay 148 is opened at the upper right contact of sequence switch spring 239 and this relay de-energizes, in turn causing the deenergization of relay 149. When sequence switch 200 leaves position 2, relay 501 energizes when interrupter spring 504 engages its lower contact in the same manner as explained at the beginning of the test, and when the interrupter contact is broken relays 501 and 502 energize in series. When interrupter spring 504 next engages its lower contact, stepping relay 207 energizes as before, closing a circuit for energizing group stepping magnet 726. When interrupter spring 504 disengages its lower contact, stepping relay 207 releases, in turn re-

leasing magnet 726 which causes the brush assembly of the first group switch to advance to the third terminal. The test of the district selector circuit associated with this terminal proceeds in the same manner as that of the first district selector circuit. When this selector circuit is satisfactorily tested, magnet 726 reenergizes, advancing the brush assembly of the group switch to the fourth terminal. This procedure is repeated until all the district selector circuits associated with the first group switch have been tested. It should be noted here that as the brush assembly of a group switch is stepping over terminals 1 to 21, inclusive, a circuit is in existence from grounded battery, brush arm 731 and its associated contacts, conductor 746, inner left armature and back contact of relay 745, conductor 747, winding of relay 748 to ground, energizing and maintaining this relay energized. Relay 748 upon energizing, prepares a circuit for the restoration of the group switch to normal when the return-to-normal key 13 is operated. This circuit may be traced from grounded battery, winding of stepping magnet 726, conductor 725, outer right armature and back contact of relay 745, right armature and front contact of relay 748, conductor 42, interrupter spring 38, contact of return-to-normal key 13, conductor 152, outer right contact of relay 103, conductors 151 and 176, lower contact of sequence switch spring 226, to ground. Relay 748 also completes a circuit from grounded battery, winding of relay 745, left inner armature and front contact of relay 748, winding of relay 748, to ground. Relay 745 does not energize in this circuit due to the fact that a shunt circuit is in existence from grounded battery, brush arm 731 and its associated contact, conductor 746, inner left armature and back contact of relay 745, conductor 747, winding of relay 748, to ground. Relay 748 also completes a circuit from grounded battery, through its outer left armature and front contact, conductors 762 and 763, right armature and back contact of relay 721, conductor 712, winding of off-normal relay 713, to ground holding relay 713 energized after the associated master switch leaves terminal 1 and lights the off-normal lamp 714 as described above.

55 When the brush assembly of the first group switch steps off terminal 21 onto terminal 22, the shunt circuit around the winding of relay 745 is opened at brush arm 731, permitting this relay to energize and holding relay 748 energized. A circuit is completed from grounded battery, winding of the first master selector switch magnet 705, conductors 719 and 720, outer left armature and back contact of relay 721, conduc-

tors 722, and 723, inner right armature and front contact of relay 745, conductor 646, normal contact of return-to-normal key 13 to ground, energizing stepping magnet 705. When the contact of interrupter 504 is broken, stepping relay 207 deenergizes and the brush assembly of the first master switch is stepped to the next terminal and a shunt circuit around relay 745 is re-established, causing this relay to deenergize. Relay 745 upon deenergizing, opens at its left contacts the energizing circuit of relay 748, causing this relay to deenergize. The deenergization of relay 748 opens at its outer left armature and front contact the energizing circuit of relay 713, which deenergizes, in turn extinguishing off-normal lamp 714. This lamp remains extinguished until the relay corresponding to relay 748 associated with the second group switch is energized. The brush assembly of the class stepping switch is caused to step one terminal every time sequence switch 200 completes a test of a district selector circuit with its repeating coil out. The energizing circuit for stepping magnet 615 extends from grounded battery, winding of the stepping magnet, conductor 242, left armature and back contact of relay 295, conductor 20, upper contacts of sequence switch spring 57, conductor 241, right armature and back contact of relay 213, conductor 240, lower contacts of sequence switch spring 221, to ground. The stepping magnet is held energized through positions 3 and 4 of sequence switch 200. When the sequence switch leaves position 4, the energizing circuit is broken, stepping the brush assembly of the class switch to the next terminal. When all the district selector circuits associated with the first group switch have been tested, the brush assembly of the class switch rests on terminal 21. The energizing circuit of relay 126 is broken at brush arm 604, causing this relay to deenergize. A circuit is then completed from grounded battery, winding, armature and back contact of stepping magnet 615, conductor 647, armature and back contact of relay 126, conductor 607, brush arm 603, and terminal 21 to ground. Magnet 615 is energized and deenergized in this circuit, stepping the brush assembly of the class selector switch to terminal 1.

With the first master switch resting on its second terminal, the twenty district selector circuits associated with the second group switch (not shown on the drawing for the sake of clarity of disclosure) are tested in the same manner as described for those of the first group switch. This procedure is continued for each succeeding group until the brush assembly of the master switch rests on its twenty-first terminal preparatory to testing the twentieth

group controlled by magnet 800 shown in Fig. 5.

It will now be assumed that the districts connected to this group switch are of the flat rate type, that is, there is no individual charge (either message register or coin collect) for originating a call.

The operation of the circuit is the same as previously described for the first group switch up to the first energization of class relay 108.

A circuit is then established from grounded battery, winding of the stepping magnet 800, conductor 807, brush arm 702 and its associated twenty-first terminal, conductor 215, to ground on sequence switch spring 209 as previously described. Magnet 800 energizes and upon the next operation of interrupter 504, relay 207 deenergizes, causing in turn the deenergization of magnet 800. The brush assembly of the twentieth group switch is thus stepped to its first terminal. Relay 108 deenergizes. Upon the next closure of interrupter 504, relay 108 and magnet 800 are reenergized. Relay 121 is energized from grounded battery on conductor 128, conductor 137, winding of relay 121, conductor 136, inner right armature and front contact of relay 108, conductors 112 and 833, brush arm 806 and its associated contact, conductor 772, brush arm 706 and its associated twenty-first terminal, conductor 513, right armature and back contact of relay 512, conductor 327, outer right armature and back contact of relay 313, conductor 511, inner right armature and back contact of relay 509, conductors 326 and 325, outer right armature and front contact of relay 317, conductors 609 and 16, lower contacts of sequence switch spring 57, conductor 608, to ground through brush arm 603 and its associated contact. Relays 126 and 131 are then energized, the circuit of relay 126 extending through the outer left armature and front contact of relay 121 and that of relay 131 extending through the outer right armature and front contact of relay 121. Relay 121 is locked through its inner left armature and front contact to ground on conductors 105, 106 and 107 at the normal contact of key 13. Relay 126 performs the same functions as described for the test of single party districts.

When stepping relay 207 next deenergizes, magnet 800 is deenergized, stepping the brush assembly of the twentieth group switch to its second terminal.

The energization of relay 131 completes a circuit from grounded battery, winding of the power magnet of sequence switch 50, conductor 19, upper contact of sequence switch spring 52, conductor 142, inner right armature and front contact of relay 121,

conductor 140, inner right armature and front contact of relay 131 to ground, for moving this sequence switch out of position 1 and into position 11.

The test now proceeds in the same manner as described for single party districts, except that conductors 772, 807, 774, 775, 776 and 777 are used instead of conductors 733, 725, 741, 743, 736 and 738, respectively. The district shown in Fig. 11 is also employed, the only difference being that battery 949 is not connected to the sleeve conductor and sequence switch springs 948 and 901 are not closed in position 17. Conductors 829, 830, 831 and 832 are substituted, respectively, for conductors 768, 740, 744 and 739, as indicated by dotted lines in the drawing.

When sequence switch 200 reaches position 18 on its second revolution, as described for single party districts, it does not wait for the test of the message register but, with sequence switch 50 in position 12, a circuit is completed from grounded battery, winding of the power magnet of sequence switch 200, lower left contact of sequence switch spring 234, conductor 31, upper left contact of sequence switch spring 56 to ground, for moving this sequence switch out of position 18 and into position 1.

The selection of a second master switch will now be described. When all of the flat rate type district selector circuits associated with the 20th group switch associated with the first master switch have been tested, the stepping magnet associated with the 20th group switch is energized in a circuit extending from grounded battery, winding of stepping magnet 800, conductor 807, brush arm 702 of the master switch and its associated 21st terminal, conductor 215, outer left armature and back contact of relay 213, left armature and front contact of stepping relay 207 in its energized condition, upper left contact of sequence switch spring 209, (with sequence switch 200 in position 2) to ground. When this circuit is broken at the contact of stepping relay 207, due to the action of interrupter spring 504, the brush assembly of the 20th group switch is advanced to its normal terminal.

When the interrupter spring engages its upper contact, a circuit is established from ground on conductor 505 as previously traced, upper contact of interrupter spring 504, conductor 595, inner left armature and front contact of relay 502, conductors 596 and 817 outer left armature and front contact of relay 809, which at this time is energized, normal terminal and brush arm 805 of the 20th group switch, inner left armature and front contact of relay 809, winding of relay 809, to battery. The winding of relay 808, which up to this time has remained energized, is shunted by the closure of this circuit and

deenergizes. Relay 809 is held energized over this circuit.

With relay 809 energized, circuits may be traced from grounded battery, winding of stepping magnet 756 of the second master switch, conductors 764 and 765, outer left armature and back contact of relay 757, conductor 828, inner right front contact of relay 809, conductor 827, to conductor 646; and from grounded battery, winding of stepping magnet 705 of the first master switch, conductors 719 and 720, outer left armature and back contact of relay 721, conductors 722 and 723, inner right armature and front contact of relay 809, conductor 819, to conductor 646 to ground on the normal contact of return-to-normal key 13. Magnets 705 and 756 are energized and when interrupter spring 504 disengages its upper contact, the holding circuit through relay 809 is broken, in turn opening the energizing circuits of magnets 705 and 756. The brush assembly of the first master switch is restored to normal and that of the second master switch is advanced from its normal terminal in the well known manner.

The test circuit is now in condition to test the districts connected to the first group switch associated with the second master switch. It will be assumed that these are of the two-party message rate type as shown on Figs. 12 and 13. This type district, it will be remembered, is the same as that disclosed in Figs. 2 and 3 of Patent No. 1,513, 351, granted Oct. 28, 1924 to D. M. Taggart and F. J. Scudder. The test of these districts proceeds in the same manner as described for single party districts with the exceptions noted.

With the first energization of class relay 108, a circuit is also completed from grounded battery, winding of magnet 810, conductor 701, brush arm 751 and its associated contact, inner left armature and back contact of relay 721, conductor 215, to ground on sequence switch spring 209 as previously described. Magnet 810 is energized and upon the deenergization of relay 207 it deenergizes, moving the brush assembly of the group switch to the first terminal: On the next closure of the interrupter 504, relay 108 and magnet 810 are again energized.

Conductor 110, over conductor 834, is connected to the first terminal of the arc served by brush arm 816. A circuit extends from grounded battery, brush arm 604 and its associated contact, conductors 118 and 117, thence in parallel through the windings of relays 115 and 116 to conductor 114, outer left armature and front contact of relay 108, conductors 110 and 834, brush arm 816 and its associated first terminal, conductor 749, brush arm 750 and its associated terminal, conductor 513, right armature and back con-

tact of relay 512, conductor 327, outer right armature and back contact of relay 313, conductor 511, inner right armature and back contact of relay 509, conductors 326 and 325, outer right armature and front contact of relay 317, conductors 609 and 16, lower contacts of sequence switch spring 57, conductor 608, the first terminal in the arc served by brush 603, to ground. Relays 115 and 116 are energized and lock through the inner left armature and front contact of relay 116, conductors 105, 106 and 107, through the normal contact of key 13, to ground.

Relay 131 is energized from grounded battery on conductor 118 as above traced, conductor 128, winding of relay 131, conductor 130, inner right armature and front contact of relay 116, conductors 318, 106 and 107, to ground at the normal contact of key 13. The energization of relay 131 completes a circuit from grounded battery, winding of the power magnet of sequence switch 50, upper left contact of sequence switch spring 53, conductor 144, inner right armature and front contact of relay 116, conductors 140 and 139, inner right armature and front contact of relay 131, to ground for moving this sequence switch out of position 1 and into position 5.

If, upon testing a busy condition of the district circuit, it is found that a "make-busy" plug has been inserted in a "make-busy" jack, test conductor 837 will be connected to ground at the contact of jack 1004 and sleeve conductor 836 will be connected to battery through the left contact of relay 1022, conductor 1021, lower right contact of sequence switch spring 1001, right armature and back contact of relay 1003, conductor 1062, through the right winding of relay 1002. As sequence switch 200 advances from position 2 into position 5, the energizing circuit of relay 521 is closed from grounded battery on conductor 836, brush arm 816 and its associated contact, conductor 749, brush arm 750 and its associated contact, through the winding of relay 521 to ground as described.

If the district selector circuit tests busy in regular telephone traffic, test conductor 837 and either conductor 836 or 838 (depending upon whether party 1 or 2 is busy) are connected to ground. If conductor 836 is grounded, relay 534 is energized from grounded battery, winding of relay 534, outer right armature and back contact of relay 520, conductor 536, lower left contact of sequence switch spring 231, conductor 511, outer right armature and back contact of relay 313, conductor 327, right armature and back contact of relay 512, conductor 513, brush arm 750 and its associated contact, conductor 749, brush arm 816 and its associated contact, to ground on conductor 836.

If conductor 838 is grounded, relay 535 is energized from grounded battery, winding of relay 535, conductor 495, outer left armature and back contact of relay 520, conductor 537, upper right contact of sequence switch spring 216, conductor 218, inner right armature and back contact of relay 313, conductor 314, brush arm 754 and its associated contact, conductor 778, brush arm 812 and its associated contact, to ground on conductor 838.

When sequence switch 200 leaves position 18, the ground at sequence switch spring 222 is removed, releasing the district circuit which returns to normal in the usual manner.

As sequence switch 200 enters position 18½, on its second revolution, a circuit is established from grounded battery, lower contact of sequence switch spring 203, conductor 165, left outer armature and front contact of relay 103, inner right armature and back contact of relay 157, winding of relay 159, inner right armature and front contact of relay 115, conductors 105 and 106, normal contact of key 13, to ground. Relay 159 is energized in this circuit. A circuit is also established from grounded battery, winding, armature and contact of relay 401, contact of key 416, conductors 405 and 34, normal contact of key 13, conductor 152, right outer armature and front contact of relay 103, right inner armature and back contact of relay 161 to ground, holding relay 401 energized through the third revolution of sequence switch 200. Relay 159 upon energizing, connects its winding in series with

the winding of relay 157 through its armature and front contact, conductor 168, lower contact of sequence switch spring 58, to grounded battery. When sequence switch 200 leaves position 18½, these two relays energize. 95

With sequence switch 200 in position 1 and relay 101 deenergized due to the fact that the district selector circuit has returned to normal, a circuit is established from grounded battery, winding of the power magnet of sequence switch 200, upper left contact of sequence switch spring 201, conductor 202, outer left armature and back contact of relay 301, conductor 102, armature and back contact of relay 101, conductor 6, front contact of start key 1, normal contact of control advance key 2 to ground, for advancing sequence switch 200 out of position 1 and into position 2. Sequence switch 200

1 and into position 2. Sequence switch 200 passes through positions 2 to 9 in the same manner as that already described for the first revolution of this switch. As sequence switch 200 enters position 10 and with sequence switch 1000 also in position 10, relay 266 is energized over a path which may be traced from grounded battery, winding of relay 266, conductor 267, lower right contact of sequence switch spring 220, conductor 921, contact 1026, brush 1029, conductor 1032, upper right and lower left contacts of sequence switch spring 1033, conductor 1034 and 1063 intermediate right armature and front contact of relay 1019 brush 1035 and its associated contact conductor 1014, through the stepping relay circuit of sender 1010, conductor 1016, brush 1038 and its associated contact, conductor 1037, right contacts of sequence switch spring 1039, 115 120 125 130

brush 1030, contact 1027, conductor 922, to ground at the lower left contact of sequence switch spring 221. Relay 266 causes the energization of relay 269 in the manner described for the first revolution of the sequence switch. However, on the third revolution of sequence switch 200, the energization of relay 269 completes a circuit from grounded battery, winding of relay 260, left armature and front contact of relay 269, conductor 170, left inner armature and front contact of relay 160, conductor 171, lower left contact of sequence switch spring 59, to ground.

15 Relay 260 upon energizing, establishes a circuit from grounded battery, lower left winding of district repeating coil 1041, winding of relay 1040, conductor 1060, brush arm 1061 and its associated contact, conductor 1062, lower left contact of sequence switch spring 1017, (with sequence switch 1000 in position 11) conductor 840, brush arm 813 and its associated contact, conductor 780, brush arm 753 and its associated contact, conductor 334, intermediate right armature and back contact of relay 332, conductor 257, upper left contact of sequence switch spring 229, conductor 29, contact of sequence switch spring 223, intermediate 30 armature and back contact of relay 255, right armature and back contact of relays 293, resistance 272, conductor 273, left contacts of sequence switch spring 225, armature and front contact of relay 260, conductor 588, winding of relay 350, conductors 589 and 170, to ground over the path described, energizing relay 350. Sequence switch 200 advances out of position 10 and into position 13 in the manner described for 35 its first revolution. Sequence switch 200 is advanced out of position 13 and into position 14 over a circuit which may be traced from grounded battery, winding of the power magnet of sequence switch 200, lower 40 right contact of sequence switch spring 234, conductors 156 and 158, upper left contact of sequence switch spring 59, to ground. In position 14, the supervisory relay 1040 in the district circuit is energized and deenergized, and sequence switch 200 is advanced 45 into position 15 in the manner already described. Sequence switch 200 is then advanced into position 18 over the same circuit by which it advanced from position 13 into 50 position 14. In position 18, with relay 350 in its energized condition, a circuit is established from grounded battery, right winding of relay 1002, conductor 1062, outer left armature and front contact of relay 1047, which is now in its operated condition, lower left contact of sequence switch spring 1001, (with sequence switch 200 in position 55 12) conductor 1021, left armature and front contact of relay 1022, conductor 838, brush arm 812 and its associated contacts, conduc-

tor 778, brush arm 754 and its associated contact, conductor 314, right inner armature and back contact of relay 313, conductor 218, right contact of sequence switch spring 216, conductor 537, outer left armature and 60 front contact of relay 520, conductor 550, upper right contact of sequence switch spring 236, conductor 250, windings of relays 351 and 352, right armature and front contact of relay 350, conductor 172, outer 65 left armature and front contact of relay 157, conductor 155, lower contact of sequence switch spring 54, to ground. Relays 351 and 352 are energized in this circuit and a 70 circuit is completed from grounded battery, winding of relay 560, conductors 561 and 562, inner right armature and back contact of relay 244, conductor 298, left armature and back contact of relay 578, conductor 587, armature and front contact of relay 331, right armature and front contact of relay 350, to ground on conductor 172 as 75 above traced. Sequence switch 200 is now returned to normal in the same manner as described for its return after the second revolution on the test of the single party message rate district.

The brush assembly of the group switch controlled by magnet 810 is stepped to the next terminal in a manner similar to that controlled by magnet 756 described above, and all of the district selectors associated with the first group switch are tested in turn. When the last district selector circuit has been tested, circuits are established for connecting the group switch associated with magnet 820 to the test circuit in the same manner as described in connection with the group switch associated with magnet 726.

It will be assumed that the selector circuits connected to this group switch are of the coin collect type similar to that disclosed in Fig. 2 of Patent No. 1,504,261, granted Aug. 12, 1924 to E. H. Mills. The operation will be the same as that described for single party message register districts with the exception that Fig. 14 will be used instead of Fig. 11. Several circuit changes will also be noted.

Upon the energization of relay 108, preparatory to setting the class switch, a circuit is established from grounded battery, brush arm 604 and its associated contact, conductors 118 and 128, winding of relay 119, conductor 138, outer right armature and front contact of relay 108, conductors 113 and 835, brush arm 826 and its associated first terminal, conductor 781, brush arm 750 and its associated twenty-first terminal, conductor 513, right armature and back contact of relay 512, conductor 327, outer right armature and back contact of relay 313, conductor 511, inner right armature and back contact of relay 509, conductors 326 and 325,

outer right armature and front contact of relay 317, conductors 609 and 16, lower contacts of sequence switch spring 57, conductor 608, brush arm 603 and its associated contact, to ground. Relay 119 is energized in this circuit. Relays 126 and 131 are then energized, the circuit of the former extending through the outer right armature and front contact of relay 119 and that of the latter extending through the inner right armature and front contact of relay 119. In position 18 of the second revolution of sequence switch 200, and in position 15 of sequence switch 50, a circuit is established from the source of coin collect current in sender 1110, conductor 1111, sender selector brush 1107 and its associated contact, outer left armature and front contact of relay 1119, conductor 1108, lower left contact of sequence switch spring 1109, (in position 17) conductor 842, brush arm 824 and its associated contact, conductor 787, brush arm 752 and its associated contact, conductor 742, outermost right armature and back contact of relay 332, conductor 333, lower right contact of sequence switch spring 225, conductor 297, outer right armature and back contact of relay 342, winding of relay 340, conductor 343, upper right contact of sequence switch spring 56, to ground. Upon the application of coin collect current by the sender circuit, relay 340 energizes, completing a circuit from grounded battery, winding of relay 560, conductors 561 and 562, inner right armature and back contact of relay 244, conductor 298, left armature and back contact of relay 578, conductor 587, armature and front contact of relay 340, to ground over the path described. Relay 560, upon energizing, causes the energization of relay 564, as above explained. When the coin collect-current circuit is opened through the district selector circuit, relay 340 de-energizes, in turn causing the deenergization of relay 560. A circuit is then established from grounded battery, winding of the power magnet of sequence switch 200, lower right contact of sequence switch spring 235, conductor 566, right armature and front contact of relay 564, left armature and back contact of relay 560 to ground, advancing sequence switch 200 out of position 18 and into position 1.

When the 20th group switch associated with the last master switch is stepped to terminal 21, circuits are established for energizing its stepping magnet in parallel with that of the stepping magnet of the first master switch through the upper contact of interrupter 504. When the interrupter contact is opened, the relay corresponding to relay 809 associated with the 20th group switch, that is, relay 847, deenergizes, in turn deenergizing the two master switch magnets. The brush assembly of the first

master switch is stepped to terminal 1 and that of the last master switch, to normal.

A circuit now extends from grounded battery, winding of relay 302, normal contact of end-of-cycle key 337, right inner armature and front contact of relay 335, (which, it will be remembered, energized in position 6 of sequence switch 200 and locked to ground on key 13,) conductor 724, terminal 1 and brush arm 702 of the first master switch, conductor 215, outer left armature and back contact of relay 213, left armature and front contact of relay 207, when it energizes due to the action of interrupter 504, upper left contact of sequence switch spring 209 to ground, energizing relay 302 and illuminating lamp 356 as an indication to the operator that a cycle of tests has been completed. Relay 302 locks through its left armature and front contact to ground on conductor 318. Relay 302, at its right armature and back contact, opens the energizing circuit of relays 501 and 502 to prevent their energization when interrupter spring 504 next engages its lower contact. No other cycle of tests will be made by this test circuit unless key 337 is operated. The function of this key will be more fully described hereinafter.

If another cycle of tests is not to be made at this time, the operator, upon noting the illumination of lamp 356, operates the return-to-normal key 13. The operation of this key opens the energizing circuit of lamp 356 at its normal contact, extinguishing the lamp. The operation of key 13 also completes the circuits from grounded battery, through the winding of relays 721, 757 and the corresponding relays associated with the other master switches, conductor 766, to ground on the front contact of return-to-normal key 13, energizing these relays. A circuit is also established from grounded battery, winding of the power magnet of sequence switch 200, upper right contact of sequence switch spring 201, conductors 247 and 597, front contact of return-to-normal key 13 to ground, advancing sequence switch 200 from position 2 to normal. As sequence switch 200 enters position 2 $\frac{3}{4}$ on its return to normal, a circuit is completed from grounded battery, winding of relay 332, conductor 357, normal contact of control advance key 2, conductor 40, operated contact of return-to-normal key 13, conductors 41 and 528, upper left contact of sequence switch spring 237, to ground. Relay 332 is energized in this circuit, and at its outermost right armatures and back contacts opens the tip and ring conductors extending to the district selector circuit, to prevent undesirable clicks from entering the district selector circuits when the group switches are stepping over busy terminals. The return-to-normal key 13 also establishes a cir-

cuit from grounded battery, brush arm 602 and terminal 1 of the class switch, conductor 606, operated contact of key 13, conductor 14, left contact of sequence switch 5 spring 216, conductor 218, inner right armature and back contact of relay 313, conductor 314, brush arm 709 and its associated 10 first terminal, conductors 711 and 712, winding of relay 713 to ground, energizing this 15 relay. The energization of relay 713 lights lamp 714 in its usual manner and establishes a circuit from grounded battery, winding, armature and back contact of stepping magnet 705 of the first master switch, normal 20 contact of key 759, right armature and front contact of relay 713, conductor 767, operated contact of key 13, to ground. Magnet 705 interrupts its own circuit, stepping the brush assembly of the first master switch 25 to normal. Each time the brush assembly of the master switch steps from one terminal to the next, the relay corresponding to relay 748 associated with the group switch connected to the terminal of the master switch, energizes over its usual circuit, closing a 30 circuit from grounded battery through its outer left armature and front contact, conductors 762 and 763, right armature and back contact of relay 721, conductor 712, winding of relay 713 to ground, holding relay 713 energized; but the brush assemblies of the group switches do not move off their 35 normal terminals.

If class sequence switch 50 fails to return 40 to its normal position when the brush assembly of the first master switch is standing on terminal 1, a circuit is established from grounded battery, winding of relay 103, conductor 153, upper contacts of sequence switch spring 55, conductor 35, outer left armature and back contact of relay 509, conductor 571, lower contact of sequence switch spring 239, to ground. Relay 103 energizes and locks through its inner left 45 armature and front contact, conductor 164, upper right contact of sequence switch spring 54, to ground. Relay 103 upon energizing, completes a circuit from grounded battery, lower contact of sequence switch 50 spring 203 when sequence switch 200 enters position 18½, conductor 165, outer left armature and front contact of relay 103, conductor 166, outer right armature and front contact of relay 157, conductor 167, winding of relay 161, to ground. Relay 161 55 is energized locking to battery through its inner left armature and front contact, conductor 175, the upper right contact of sequence switch spring 58 and completes a circuit from grounded battery, winding of the power magnet of sequence switch 50, upper right contact of sequence switch spring 53, conductor 39, inner right armature and front contact of relay 161, to

ground. Sequence switch 50 will then be returned to normal over this circuit. Return-to-normal key 13 is then restored to its normal position, causing the deenergization of relays 332, 721, and 757, and the entire circuit is returned to normal in an obvious 65 manner.

A cycle of tests may be interrupted before its conclusion and the entire circuit returned to normal by restoring start key 1 to normal and operating return-to-normal key 13. 75 Start key 1, upon its restoration, opens at its operated contact the circuit for advancing sequence switch 200 out of position 1 at the conclusion of the test then being performed at the district selector circuit. Key 80 13, in addition to causing the same series of operations as above described, also completes a circuit from grounded battery, winding of the stepping magnet of the group switch to which the district selector circuit under test 85 is connected, normal contact of the relay corresponding to relay 745, or relay 809, front contact of the relay corresponding to relay 748 or relay 808, conductors 818 and 42, interrupter spring 38 and its normal contact, 90 operated contact of return-to-normal key 13, conductor 152, outer right normal contact of relay 103, conductors 151 and 176, lower contact of sequence switch spring 226 to ground. The stepping magnet of the associated group switch is energized in this circuit, and when the contact of interrupter 38 is opened, the 95 magnet deenergizes, moving the brush assembly of the switch to the next terminal. This operation is repeated and the brush assembly of the group switch steps from terminal to terminal until it rests on terminal 100 21. With the brush assembly on this terminal, the shunt circuit around the relay corresponding to relays 745 or 809 is broken, 105 permitting the energization of that relay. The energizing circuit of the stepping magnet is opened, preventing the further advance of the switch. The further restoration takes place in a similar manner to that already described. 110

It will now be assumed that it is desired to test a particular district selector circuit out of all the district selector circuits connected to the group switches. The keys shown in Fig. 10 are of the mechanically locked and magnetically released type. When a key in any of the four rows is depressed, it is mechanically locked, causing its corresponding key release magnet to close its back contact. Upon the energization of the key release magnets, the keys are released opening the back contacts. 115

Each group switch is arranged to have access to 20 districts and each master switch has access to 20 groups. Therefore each master switch controls 400 districts and it is necessary to provide 10 master switches. All 120 125

10 switches have not been shown in the drawing because it was not thought necessary for a full understanding of the invention. Keys 850 to 853, inclusive, control the 5 selection of zero to three thousand, respectively. Keys 860 to 869, inclusive, control zero to nine hundred, respectively, keys 870 to 879, inclusive, control zero to nine tens, respectively and keys 880 to 889 control zero 10 to nine units respectively. A particular selector circuit is thus indicated by depressing one key in each of the four rows of keys.

Particular circuit key 3 and start key 1 are operated and the set of numerical keys 15 corresponding to the number of the district selector circuits desired, are also operated. Let it be assumed that it is desired to test district Number 0380. Since the first master switch controls 400 districts, that is, districts 20 numbered 0 to 399, it is seen that district Number 0380 is found on the first terminal of the last group switch controlled by the first master switch. This group switch is associated with districts of the flat rate type, 25 as shown on Fig. 11.

To select this particular district selector circuit, keys 850, 863, 878 and 880 are depressed. A circuit is established from 30 grounded battery, winding of the power magnet of sequence switch 600, contact of sequence switch spring 630, conductor 43, operated contact of particular circuit key 3, to ground, for moving this sequence switch out of position 1 and into position 2. A circuit 35 is also closed from grounded battery, winding of relay 635, conductor 649, operated contact of key 863, conductor 856, right armature and back contact of relay 855, conductor 648, operated contact of particular 40 circuit key 3, conductor 11, normal contact of repeat key 12 to ground, energizing relay 635. A third circuit is completed from 45 grounded battery, winding of relay 307, left armature and back contact of relay 305 conductors 211 and 44, operated contact of key 3, conductor 650, lower contact of sequence 50 switch spring 631, conductors 106 and 107, normal contact of key 13, to ground. Relay 307 is energized in this circuit and through 55 its inner armature and front contact connects its winding in series with relay 305, to ground over conductors 312 and 106, through the normal contact of key 13. When the energizing circuit of relay 307 is 60 opened at sequence switch 631 on the advance of sequence switch 600 out of position 1, relay 305 energizes.

The operation of the start key completes the usual circuit for advancing sequence switch 200 out of position 1 and into position 2 and also establishes a circuit through the winding of relay 401, which energizes and performs its usual function.

The energization of relay 635 establishes

a circuit from grounded battery, left armature and back contact of relay 622, winding of relay 623, lower contact of sequence switch spring 626, brush arm 642 and one of the first fifteen terminals associated therewith, to ground at the armatures and front 65 contacts of relay 635, energizing relay 623. Relay 624 is also energized to the same ground through the left upper contact of sequence switch spring 626. A circuit may be traced from ground, right winding of relay 622, right armature and front contact of relay 623, conductor 653, brush arm 638 and its associated contacts, winding of stepping magnet 636, to grounded battery for energizing this magnet. A circuit is also completed 70 from ground, through the left winding of relay 622, left armature and front contact of relay 623, right contacts of sequence switch spring 625, conductor 654, left armature and back contact of relay 855, conductor 857, 75 operated contact of hundreds key 863, conductor 858, operated contact of thousands key 850, conductors 859, 723 and 722, outer left armature and back contact of relay 721, conductors 720 and 719, winding of the 80 master stepping magnet 705 to grounded battery, energizing this magnet. The energization of relay 624 opens the energizing circuit of register stepping magnet 636. This circuit extends from grounded battery, winding of stepping magnet 636, brush arm 638 and its associated contacts, conductor 653, armature and back contact of relay 624, right contacts of sequence switch spring 628, conductor 660, armature and back contact of stepping magnet 636, conductor 655, armatures and back contacts of key release magnets 854, 890, 891 and 892, to ground. In position 2 of sequence switch 200, a circuit 85 is also established from grounded battery, 90 lamp 645, brush arm 640 and its associated contact, upper contact of sequence switch spring 629, conductors 656 and 655, to ground at the contacts of the key release magnets. Lamp 645 is illuminated as an indication that the master switch is being 95 selected.

The closure of circuits through both windings of relay 622, already traced, causes this relay to energize, opening at its left armature and back contact the circuit of relay 623 which deenergizes. The deenergization of relay 623 in turn opens the energizing circuits of relay 622 and stepping magnets 636 and 705. The deenergization of the stepping magnets causes their corresponding brush assemblies to step to the next terminals. The circuits through relays 623 and 622 are closed and opened alternately as the brush assembly associated with stepping magnet 636 steps from terminal to terminal. When the brush assembly of the register switch 636 steps to the 16th terminal of the 100

arc served by brush 642, the energizing circuit for stepping magnet 636 will extend over conductor 449, normal contacts of tens keys 870, 871, 872, 873, 874, 875, 876, and 877, operated contact of keys 878, conductor 648, operated contact of key 3, conductor 11, normal contact of key 12 to ground. The brush assembly of the register switch is stepped two terminals because of this ground. A circuit for magnet 705 extends from grounded battery, winding of magnet 705, conductors 719 and 720, outer left armature and back contact of relay 721, conductors 722, 723 and 859, operated contact of key 850, conductor 858, operated contact of key 863, conductor 857, left armature and back contact of relay 855, conductor 654, right contacts of sequence switch spring 625, left armature and front contact of relay 623, left winding of relay 622 to ground. The purpose of this is to make allowance in the setting of the master switch for the first two terminals on the arcs which are not connected to group switches. The 18th and 25 19th terminals of the arc served by brush arm 642, are also grounded over conductors 450 and 451, respectively, normal contacts of keys 870, 871, 872, 873, 874, 875, 876 and 877, operated contact of key 878, conductor 648, to ground over the path previously traced. The brush assemblies of the register and master switches will thus be stepped to the 21st terminal, which, it will be seen, is connected to the proper group switch. 30 The 21st terminal in the arc served by brush 642 will be found to be ungrounded, conductor 452 being opened at the contacts of keys 870 to 879. The circuit of relay 624 is therefore opened, causing the deenergization of this relay. A circuit is then established from grounded battery, winding of stepping magnet 636, brush arm 638 and its corresponding terminals, conductor 653, armature and back contact of relay 624, right contacts of sequence switch spring 628, conductor 660, armature and back contact of stepping magnet 636, to ground on conductor 655, stepping the brush assembly associated with the register switch stepping magnet 636 to the 55 22nd terminal. A circuit now extends from grounded battery, winding of stepping magnet 636, brush arm 638 and the corresponding 22nd terminal, conductor 658, winding of relay 620, right armature and back contact of relay 622, upper left contact of sequence switch spring 631, conductor 106, normal contact of key 13, to ground. Relay 620 is energized in this circuit but, due to the fact of the high resistance of its winding, stepping magnet 636 does not energize. The energization of relay 620 completes a circuit from grounded battery, winding of the power magnet of sequence switch 600, upper right contact of sequence switch spring 627, conductor 659, armature and

front contact of relay 620, to ground over the path previously described for moving sequence switch 600 out of position 2 and into position 3.

A circuit is now established from 70 grounded battery, winding of stepping magnet 636, brush arm 638 and its corresponding 22nd terminal, conductor 658, upper contacts of sequence switch spring 628, conductor 660, armature and back contact of 75 stepping magnet 636, to ground on conductor 655. Ground on conductor 658 short circuits the winding of relay 620, causing it to deenergize. The brush assembly of the register switch is now stepped to its normal 80 position. A circuit is now completed from ground on conductor 655, conductor 656, upper contact of sequence switch spring 629, brush arm 640 and its associated normal contact, conductor 661, lower left contact of sequence switch spring 627, winding of the power magnet of sequence switch 600 to grounded battery, moving this sequence switch out of position 3 and into position 4. As sequence switch 600 enters position 4, a 85 circuit is also closed from grounded battery, winding of relay 108, conductor 109, upper right contact of sequence switch spring 631, conductors 106 and 107, normal contact of key 13 to ground energizing relay 108. A 90 circuit is also established from grounded battery, lower right contact of sequence switch spring 628, conductor 299, winding of relay 295, conductor 45, operated contact of particular circuit key 3, conductor 662, lower left and upper right contacts of sequence switch spring 619, right armature and back contact of relay 622, upper left contact of sequence switch spring 631, conductors 106 and 107, normal contact of key 13, to ground. Relay 295 is energized in this 95 circuit and locks to ground at its right armature and front contact. A circuit is also closed from ground on the normal contact of key 13, conductors 107 and 106, upper 100 right contact of sequence switch spring 631, conductor 109, brush arm 643 and its associated first contact, conductor 664, upper contacts of sequence switch spring 626, thence through the windings of relays 623 and 624 105 in parallel to grounded battery as previously described, energizing these relays. A circuit is now completed from grounded battery, winding of magnet 636, brush arm 638 and its associated contact, conductor 653, 110 right armature and front contact of relay 623, right winding of relay 622 to ground, energizing magnet 636. A circuit is also established from grounded battery, winding of magnet 800, conductor 807, brush arm 702 115 and its associated contact, conductors 215 and 306, upper contacts of sequence switch spring 625, left armature and front contact of relay 623, left winding of relay 622 to ground, energizing magnet 800. Relay 622 120

125 130

is now energized through both windings causing the deenergization of relay 623. As a result magnets 636 and 800 deenergize, moving the brush assemblies of the register and group switches to their first terminals.

Since the first terminal of the arc served by brush 643 is strapped to the normal terminal, relay 623 is energized over the same circuit described above, causing the energization of magnet 636 and 800. The energization of relay 622 causes the deenergization of relay 623 and the subsequent deenergization of magnet 636 and 800, moving the corresponding brush assemblies to the second terminals.

As soon as the brush assembly of the group switch 800 reaches its first terminal, a circuit is closed from grounded battery, brush arm 604 and its associated contact, conductors 118, 128 and 137, winding of relay 121, conductor 136, inner right armature and front contact of relay 108, conductors 112 and 833, brush arm 806 and its associated contact, conductor 772, brush arm 706 and its associated contact, conductor 513, right armature and back contact of relay 512, conductor 327, outer right armature and back contact of relay 313, conductor 511, inner right armature and back contact of relay 509, conductors 326, and 663, upper contacts of sequence switch spring 611, conductors 610 and 16, lower contacts of sequence switch spring 57, conductor 608, brush arm 603 to ground, energizing relay 123 which locks through its inner left contact to ground on conductor 106. A circuit is then established from battery on conductor 118, conductors 128 and 127, winding of relay 131, conductor 130, outer right armature and front contact of relay 121, conductors 106 and 107, normal contact of key 13 to ground, energizing relay 131. The energization of relay 131 closes a circuit from grounded battery, winding of the power magnet of sequence switch 50, conductor 19, upper left contact of sequence switch spring 52, conductor 142, inner right armature and front contact of relay 121, conductors 140 and 139, inner right armature and front contact of relay 131 to ground, for moving this sequence switch into position 11. A circuit is also completed from ground on the normal contact of key 13, conductors 107 and 106, upper left contact of sequence switch spring 631, right armature and back contact of relay 622, upper contacts of sequence switch spring 619, conductor 665, left armature and front contact of relay 295, conductor 242, winding of class stepping magnet 615, to grounded battery, energizing this magnet. As relay 622 energizes and deenergizes in the manner previously described, relay 623 and stepping magnet 615 deenergize and the brush assembly of the class switch is moved to its second terminal.

As soon as sequence switch 600 reached position 5, a circuit was established from grounded battery, lamp 644, brush arm 641 and its associated contact, conductor 667, lower right contact of sequence switch 70 spring 629, conductor 656 to ground on conductor 655, causing lamp 644 to be illuminated as an indication that group selection is being made.

It will be noted that the energizing circuit for relay 623 is opened through terminals 3 to 12 inclusive in the arc served by brush arm 643 since conductor 415 associated therewith is not connected to the operated contact of key 878. The brush assembly of 80 the group switch will therefore remain on the second terminal to which is connected the particular district circuit to be tested.

With the register switch on its third terminal, relay 624 deenergizes and a circuit is closed from grounded battery, winding of magnet 636, brush arm 638 and its associated contact, conductor 653, armature and back contact of relay 624, right contacts of sequence switch spring 628, conductor 660, 90 armature and back contact of magnet 636, conductor 655, to ground through the contacts of key release magnets 854, 890, 891 and 892. Magnet 636 interrupts its own circuit through its back contact and the register switch is stepped to terminal 95 22.

With the brush assembly of the register switch resting on the 22nd terminal, a circuit is established from ground on the normal contact of key 13, conductor 106, upper 100 left contact of sequence switch spring 631, right armature and back contact of relay 622, winding of relay 620, conductor 658, 105 22nd terminal of the arc served by brush 638, winding of stepping magnet 636, to grounded battery. Relay 620 energizes in this circuit but stepping magnet 636 does not receive sufficient current through the winding of relay 620. A circuit then extends from grounded battery, winding of the power magnet of sequence switch 600 right upper contact of sequence switch spring 627, conductor 659, armature and front contact of relay 620, right armature and back contact of relay 622, to ground over the path 110 previously traced, for advancing sequence switch 600 out of position 5 and into position 6. Ground on sequence switch spring 632 carries the switch to position 18. Sequence switch 600 and register switch 636 115 remain in position 18 and on the 22nd terminal, respectively, until particular circuit key 3 is restored to normal.

When sequence switch 600 enters position 6, as above described, a circuit extends from grounded battery, winding of the power magnet of sequence switch 200, lower left contact of sequence switch spring 201, conductor 219, upper left and lower right contacts of sequence switch spring 613, to 120 130

ground for moving this sequence switch out of position 2 and into position 5. With sequence switch 200 in position 5, a test of the particular district circuit with the repeating coil out, proceeds in the same manner as that described for the automatic test of the district selector circuit. It should be noted that as sequence switch 600 advances through positions 10 to 15, a circuit is established from grounded battery, contact of sequence switch spring 621, conductor 414, windings of key release magnets 854, 890, 891 and 892 in parallel, to ground, energizing these magnets and releasing the operated 10 numerical keys.

After the conclusion of the test with the repeating coil out, the test with the repeating coil in, may be made in the following manner: Particular circuit key 3 is restored to 20 normal, completing a circuit from ground, through its normal contact, conductor 668, lower right contact of sequence switch spring 627, winding of the power magnet of sequence switch 600, to grounded battery, for 25 moving this sequence switch out of position 18 into position 1. With sequence switch 600 in position 1, a circuit is established from grounded battery, winding of stepping magnet 636, brush arm 639 and its associated 30 contact, conductor 657, normal contact of key 3, conductor 660, armature and back contact of stepping magnet 636, lower contacts of sequence switch spring 611 to ground, energizing magnet 636, which 35 interrupts its circuit at its own back contact, stepping the brush assembly of the register switch to its normal terminal.

It will be remembered that relay 295 was energized upon the operation of key 3. A 40 circuit was then completed from grounded battery, winding of stepping magnet 615, conductor 242, left armature and front contact of relay 295, conductor 665, upper contacts of sequence switch spring 619, right 45 armature and back contact of relay 622, upper left contact of sequence switch spring 631, conductors 106 and 107 to ground on the normal contact of key 13. Therefore, every time relay 622 energized and deenergized as previously described, magnet 615 moved the brush assembly of the class stepping switch one terminal. The class switch thus follows the group switch on a particular setting and is able to change the setting 50 of the class circuit when a new group switch is encountered. After the completion of the test of the district selector circuit with the repeating coil in, the routine test of the succeeding district selector circuits may be continued. At the completion of the second or 60 third revolution of test sequence switch 200, a circuit is completed from grounded battery, winding of the stepping magnet of the group switch in which the particular district circuit appears, through the brush arm of the 65

master selector switch controlling the particular group, conductor 215, outer left armature and back contact of relay 213, left armature and front contact of relay 207, upper left contact of sequence switch spring 209 to ground. As sequence switch 200 enters position 2, this circuit becomes effective and the brush assembly of the group switch is advanced to the next terminal and stepping relay 207 deenergizes as previously described. It should be remembered that as sequence switch 200 left position 18 on its second or third revolution, the holding circuit of relay 295 was opened at the lower right contact of sequence switch spring 228. 70 Relay 295 deenergizes and the routine test of the remaining district selectors progresses in the manner above outlined. When all the district selector circuits have been tested, lamp 356 is illuminated and the circuit is 75 restored to its normal condition as previously described.

The foregoing description of the selection of a particular district selector circuit did not include the motion of the group switch 80 above the first terminal connected to a circuit due to the fact that an even numbered tens key and zero units key were depressed. If, however, circuit No. 0357 had been chosen, the operation would be slightly different. After the selection of the master switch in the manner described and with the group register and class switches standing on their second terminals, the energizing circuit for relays 623 and 624 will be extended through terminals 2 to 11 of the arc served by brush arm 643, conductor 666, lower contacts of sequence switch spring 601, conductor 415, operated contact of key 875, conductor 648, to ground through the operated contact of key 3. Relays 622 and 623 will energize and deenergize alternately, causing the brush assemblies of the register and group switches to advance step by step to their 12th terminals. A circuit is now 100 closed from grounded battery, left armature and back contact of relay 622, winding of relay 623, upper right contact of sequence switch spring 626, conductor 664, brush arm 643 and its corresponding terminal, conductor 440, normal contacts of keys 881, 882, 883, 884, 885, and 886, operated contact of key 887 to ground on conductor 648 as previously traced. Relay 623 energizes and causes the brush assemblies of the register and group switches to advance to their next terminals. The 12th to the 17th terminals of the arc served by brush 643 are grounded over conductors 440, 441, 442, 443, 444 and 445, through the normal contacts of keys 881 to 886 inclusive, moving the brush assemblies of the register and group switches to the 18th terminal. Conductor 446 connected to this terminal is opened at the operated contact of key 887, arresting the ad. 110 115 120 125 130

vance of this switch. Relay 624 also deenergizes, causing the energization of stepping magnet 636. The brush assembly of the register switch is then stepped to the 22nd terminal in the manner previously described.

The district connected to the 18th terminal of the group switch is the one corresponding to No. 0357 and the test of this circuit proceeds in the same manner as above described.

It will be remembered at the beginning of this description that upon the operation of start key 1, a circuit was established from grounded battery, winding of relay 401, conductor 402 brush arm 403 and its associated normal contact, conductors 404 and 18, operated contact of start key 1 to ground, energizing relay 401 which locked through its inner left armature and front contact, normal contacts of key 416, conductors 405 and 34, normal contact of key 13, conductor 152, outer right back contact of relay 103, conductors 151 and 176, lower contact of sequence switch spring 226, to ground. The energization of relay 401 completes a circuit from grounded battery, winding of stepping magnet 400, brush arm 411 and its associated contact, outer left armature and front contact of relay 401, contact of interrupter 410, to ground. When interrupter 410 disengages its contact, the energizing circuit of magnet 400 is opened and the brush assembly of the associated switch is stepped to the next terminal. Upon the next engagement of interrupter 410 with its contact, the energizing circuit of magnet 400 is again established. This operation is repeated until the brush assembly reaches the seventeenth terminal. At this time, a circuit is completed from grounded battery, winding of relay 454, to lamp 417 and alarm register 418 in parallel, the seventeenth terminal of the arc served by brush 412, right armature and front contact of relay 401, to ground. Lamp 417 is illuminated as an indication that the progress of the test of a district selector circuit has been arrested. Register 418 is energized to record the number of times such indication has been given and relay 454, upon energizing, completes a circuit from grounded battery, armature and front contact of relay 454, alarm 455, to ground as an audible signal to the operator that trouble has developed during test. The open and closed period of interrupter 410 is so timed that a complete test of a district selector circuit should be finished before the brush assembly controlled by magnet 400 is stepped to its seventeenth terminal. Upon the operation of key 416, the holding circuit of relay 401 is opened, deenergizing this relay, in turn causing the deenergization of relay 454 and register 418 and extinguishing lamp 417.

The operation of key 13 also causes the de-

energization of relay 401, since the locking circuit of that relay was traced through the normal contact of key 13. The deenergization of relay 401 establishes a circuit from grounded battery, winding, armature and back contact of stepping magnet 400, brush arm 413 and its associated contacts, right armature and back contact of relay 401, to ground. Magnet 400 is energized in this circuit and interrupts its circuit at its armature and back contact, causing the brush assembly to step to its normal position.

An alternate arrangement of separate time alarms for busy and trouble conditions is shown on Fig. 16. When this circuit is employed, the operation of start key 1 completes a circuit from grounded battery, right armature and back contact of relay 427, winding of relay 425, brush arm 421 and its associated normal contact, conductors 406 and 18, operated contact of start key 1, to ground. Relay 425 is energized in this circuit and completes a locking circuit for itself through its own outer left armature and front contact, conductors 407 and 34, to ground at the normal contact of key 13 over the path previously described. The energization of relay 425 completes a circuit from grounded battery, winding of stepping magnet 420, brush arm 422 and its associated contacts, inner left armature and front contact of relay 425, left armature and back contact of relay 435, contact of interrupter 437, to ground. Magnet 420 is energized and when interrupter 437 opens the energizing circuit at its contact, magnet 420 deenergizes, moving the brush assembly to the next terminal. The brush assembly is thus moved one terminal every time interrupter 437 makes and breaks the energizing circuit at its contact. When the brush assembly reaches the seventeenth terminal, a circuit is completed from grounded battery, winding of relay 454, conductors 456 and 408, lamp 428, the seventeenth terminal in the arc served by brush 423, right armature and front contact of relay 425, to ground. Relay 454 performs the same function as previously described and lamp 428 is illuminated as an indication that the progress of the test has been arrested. Lamp 428 remains lighted until the operation of key 426, which, upon being operated, completes an obvious circuit for relay 427. Relay 427 opens the holding circuit of relay 425 at its right armature and back contact, causing this relay to deenergize. Relay 425 opens the circuit of lamp 428, extinguishing it, and completes a circuit from grounded battery, winding, armature and back contact of stepping magnet 420, brush arm 424 and its associated contact, right armature and back contact of relay 425, to ground. Magnet 420 is energized and at its back contact interrupt its own circuit, restoring the

brush assembly of the time alarm switch to normal. This alarm circuit takes care of the busy condition of the selector circuits. The apparatus to the right of Fig. 16 is employed for a trouble time alarm. The energization of relay 586 at the beginning of the test completes a circuit from grounded battery, winding of relay 435, brush arm 431 and its associated normal contact, conductor 570, right armature and front contact of relay 586, to ground. Relay 435 is energized in this circuit and completes a locking circuit for itself through its inner right armature and front contact, left armature and back contact of relay 427, to ground on conductor 570. A circuit is also completed from grounded battery, winding of stepping magnet 430, brush arm 432 and its associated normal contact, left armature and front contact of relay 435, through interrupter 437 to ground. Magnet 430 is deenergized and energized every time the contact of interrupter 437 is opened and closed, stepping the brush assembly of the trouble time alarm switch from terminal to terminal. When the brush assembly is stepped to the eighth terminal, a circuit is completed from ground at the outer right armature and front contact of relay 435, brush arm 433 and its associated eighth contact, lamp 429 and the winding of register 436 in parallel, conductors 408 and 456 winding of relay 454, to grounded battery. Relay 454 energizes and performs the same function as described above. Lamp 429 is illuminated and register 436 is operated to record the fact that the alarm has operated. Key 426 is now operated, completing an obvious circuit for relay 427 which locks through its left armature and front contact to ground on conductor 570. Relays 425 and 435 are deenergized. The brush assemblies of the busy time alarm and trouble time alarm switches are then returned to normal. The circuit of the latter extends from grounded battery, winding, armature and back contact of magnet 430, brush arm 434 and its associated contacts, conductor 457, outer right armature and back contact of relay 435. The release of key 426 or the operation of either key 13 or key 2, causes the restoration of the test circuit to normal, deenergizing relay 586 and opening the circuit already traced for energizing relay 435, deenergizing relay 427.

A second cycle of routine tests may be made by the operation of key 337. The operation of this key opens the holding circuits of relays 302 and 335 and lamp 356, causing these relays to deenergize and extinguishing the lamp. A circuit is then completed from grounded battery, upper right contact of sequence switch spring 228 (with sequence switch 200 in position 2), conductor 205, right armature and back con-

tact of relay 302, conductor 303, winding of relay 501, outer left armature and back contact of relay 502, lower contact of interrupter 504, conductor 505, inner right armature and back contact of relay 103, conductor 104, normal contact of key 2, operated contact of key 1, normal contact of key 3, conductor 11, normal contact of key 12, to ground. Relay 501 is energized and connects its winding in series with the winding of relay 502 through its armature and front contact, conductor 508, inner left armature and back contact of relay 509, conductor 510, left armature and back contact of relay 358, conductor 304, upper contacts 75 of sequence switch spring 601 to ground. When the lower contact of interrupter 504 is broken, relay 502 energizes in series with relay 501. A circuit is also established from grounded battery, winding of stepping magnet 705, conductors 719 and 720, outer left armature and back contact of relay 721, conductors 722 and 723, outer right armature and back contact of relay 335, conductor 724, brush arm 702 and its 90 associated first contact, conductor 215, outer left armature and back contact of relay 213, left armature and front contact of relay 207 (which operated in response to the closure of interrupter 504 as previously described), upper left contact of sequence switch spring 209, to ground. Magnet 705 is energized and upon release of relay 207, magnet 705 deenergizes moving the brush assembly of the master switch to the second terminal. The 100 second routine test now proceeds in the same manner as described for the first routine test. If the test is halted, due to the development of trouble in either the test circuit itself or in the test selector circuit under 105 test, as indicated by the illumination of lamp 417 or 428, the progress of the test may be advanced by the operation of key 2. A circuit is completed from grounded battery, winding of the power magnet of sequence 110 switch 200, upper right contact of sequence switch spring 201, conductor 178, operated contact of key 2 to ground, advancing this sequence switch out of the position into which it has come to rest and into position 115 1. A circuit is also established from grounded battery, operated contact of key 2, conductor 47, brush arm 604 and its associated twenty-second terminal, conductor 118, through the windings of the energized 120 class relay, to ground on conductor 106. The purpose of this circuit is to hold the class relays energized when the brush assembly of the class stepping switch is resting on its twenty-second terminal. As sequence switch 125 200 is advanced from position 23/4 to 18, a circuit extends from grounded battery, winding of relay 332, conductor 357, operated contact of key 2, conductors 41 and 528, upper left contact of sequence switch spring 130

- 237, to ground. Relay 332 is energized and locks through its left armature and front contact, conductor 359, lower left contact of sequence switch spring 209, to ground. 5 Conductors 334 and 742 leading to the district circuit, are opened at the outer right armatures and back contacts of relay 332 to prevent any false operations in that circuit. Sequence switch 200 will not advance 10 out of position 1 while key 2 is in its operated position, since, it will be remembered, the energizing circuit for the power magnet of sequence switch 200 in position 1 was traced to ground at the normal contact of 15 key 2. When key 2 is restored to its normal position, sequence switch 200 advances out of position 1 and the test circuit advances to the next district in the manner previously described. 20 A test may be repeated upon a district selector circuit by the operation of key 12. A circuit is established from grounded battery, lower right contact of sequence switch spring 228, conductors 299 and 214, winding 25 and inner left back contact of relay 213, conductor 179, operated contact of key 12, to ground. Relay 213 is energized in this circuit and locks to ground at its inner left armature and front contact. The circuit 30 through the stepping magnet associated with the class switch is opened at the right armature and back contact of relay 213, and the circuit of the stepping magnet associated with the group switch to which the district 35 is connected is also opened at the outer left armature and back contact of relay 213. These magnets are thus prevented from moving the brush assemblies of the switches to their next terminals. The circuit through 40 the magnet of register 162 is also opened at the normal contact of key 12, preventing a registration from being made on a repeat test. A circuit is also completed from 45 grounded battery, operated contact of key 12, conductor 47, to the twenty-second terminal of the arc served by brush arm 604 to hold the energized class relays in that condition when the brush assembly of the class stepping switch is resting on that terminal. 50 A circuit is also established from ground on the operated contact of key 12, conductors 44 and 211, inner right armature and front contact of relay 305, left armature and back contact of relay 317, winding 55 of relay 321, conductor 205, upper right contact of sequence switch spring 228, to ground. Relay 321 is energized in this circuit and completes a circuit from 60 grounded battery, winding of the power magnet of sequence switch 200, lower left contact of sequence switch spring 201, conductor 219, left contacts of sequence switch spring 613, conductor 614, outer right armature and front contact of relay 131, conductor 65 145, outer right armature and back contact of relay 509, conductor 515, right armature and front contact of relay 321, conductor 328, left armature and back contact of relay 207, upper left contact of sequence switch spring 209 to ground, for moving 70 this sequence switch out of position 2 and into position 5. The test will then be repeated upon the same district selector and will continue to be repeated indefinitely as long as key 12 remains in the operated position. Upon the release of key 12, stepping magnet 726 is permitted to energize. A single repeat test may be made, in which case key 12 is momentarily operated. 75
- When a "make-busy" plug has been inserted in the jack associated with the district selector circuit under test as hereinbefore mentioned, the test circuit, it will be remembered, was held in position 5 until the operation of key 7. Upon the operation of this 80 key, a circuit is completed from grounded battery, winding of relay 332, conductor 357, normal contact of key 2, conductor 40, normal contact of key 13, conductor 48, operated contact of key 7, conductor 49, lower 85 left and upper right contacts of sequence switch spring 65, conductor 572, inner right armature and front contact of relay 518, which, it will be remembered, is now in its 90 energized position, inner right armature and back contact of relay 520, conductor 251, upper right contact of sequence switch spring 237, to ground. Relay 332 is energized and locks through its left armature and front contact. A circuit may now be 95 traced from grounded battery, winding of the power magnet of sequence switch 200, upper right contact of sequence switch spring 201, conductor 247, innermost right armature and front contact of relay 332, conductor 528, upper left contact of sequence switch spring 237 to ground, advancing sequence switch 200 out of position 5 and into 100 position 1. Relay 332 opens at its outer right armatures and back contacts, conductors 334 and 742 leading to the district circuit, preventing false operations in that circuit. As sequence switch 200 leaves position 18, the holding circuits for relays 518 and 512 are opened at the upper contacts of 105 sequence switch spring 237, deenergizing these relays. Relay 518 upon deenergizing, at its inner left contact, opens the circuit through lamp 533 and register 532, extinguishing the lamp and releasing the register. 110 As sequence switch 200 is passing through positions 3 and 4, a circuit is completed from grounded battery, winding of magnet 615, conductor 242, left armature and back contact of relay 295, conductor 20, upper 115 contacts of sequence switch spring 57, conductor 241, right armature and back contact of relay 213, conductor 240, lower contacts of sequence switch spring 221 to ground, energizing magnet 615. As sequence switch 120 125 130

200 leaves position 4, a circuit is opened, releasing magnet 615 and moving the brush assembly of the class switch to the next terminal, thus keeping the proper relationship between the brush assemblies of the class switch and of the group switch. Sequence switch 200, upon its return to normal, is moved out of position 1 over a circuit extending to ground on the operated contact of key 1, as previously traced; and in position 2, relays 501 and 502 are reenergized, moving the brush assembly of the group switch to the next terminal for testing. As long as key 7 is operated, the test circuit will pass the terminal of any district selector circuit which is made busy by the insertion of a plug in the associated jack.

In describing the preliminary test of the district selector circuit, it was noted that when the district selector was found busy on regular traffic, relay 541 was energized illuminating lamp 22, and sequence switch 200 came to rest in position 5, remaining there until the operation of key 8. A circuit then extends from grounded battery, winding of relay 332, conductor 357, normal contacts of key 2 and key 13, operated contact of key 8, conductor 66, outer left armature and front contact of relay 313, which, it will be remembered, is now in its operated position, conductor 251, upper right contact of sequence switch spring 237, to ground. Relay 332 is energized in this circuit and locks through its left armature and front contact to ground on conductor 359, as described in the previous operation. Relay 332 opens conductors 334 and 742 and closes the circuit for advancing sequence switch 200 into position 1 as described in the preceding paragraph. A circuit is also completed from grounded battery, winding of register 25, operated contact of key 8, conductors 23 and 544, inner right armature and front contact of relay 541, conductor 251, upper right contact of sequence switch spring 237 to ground, causing register 25 to operate. Lamp 22 is also illuminated in a circuit extending from grounded battery, lamp 22 conductor 21 to ground on conductor 544. As sequence switch 200 leaves position 8, the holding circuit for relays 313 and 541 is opened at the contact of sequence switch spring 237, causing these relays to deenergize, in turn releasing register 25 and extinguishing lamp 22. The brush assembly of the group switch is then stepped to the next terminal in the same manner as described in the preceding paragraph. As long as key 8 remains operated, the test circuit will pass the terminals of the group switch which are connected to district selector circuits which are busy in regular traffic.

The release of key 1 at any time during the progress of the test, will cause the test

circuit to cease functioning. However, the test being made at the time of the release of key 1 will be completed before the release of key 1 becomes effective. The circuit for advancing the sequence switch 200 out of position 1 at the completion of the test being made, is opened at the contact of key 1, as are also the circuits for the re-operation of relays 401, 501 and 502. The test circuit may be restored to normal after the release of key 1 by the operation of key 13. This circuit will then function as already described for the operation of key 13.

Routine tests of particular groups of district selector circuits may be omitted by the operation and release of keys 758 or 759. The operation of key 759 completes a circuit from grounded battery, winding of stepping magnet 705, conductor 719, operated contact of key 759, to ground. Magnet 705 is energized in this circuit and when key 759 is released magnet 705 is deenergized, stepping the brush assembly of the master switch to the next terminal. This operation is repeated a number of times equal to the number of terminals to be passed over. Key 758 functions similarly with respect to magnet 756.

Provision is also made for the detection of a condition arising when two master switches have been stepped off normal inadvertently. It will be assumed that the master switches associated with magnets 705 and 756 are in their "off-normal" position at the same time. It will be remembered that relays 713 and 760 are energized, and lamps 714 and 761 are illuminated. A circuit will then be established from grounded battery, resistance 716, inner left armature and front contact of relay 713, conductor 717, to conductor 718; and also from grounded battery, resistance 770, inner left armature and front contact of relay 760, to conductor 718; thence over conductor 718, right armature and back contact of relay 358, winding of relay 301, conductors 318 and 106, normal contact of key 13 to ground, energizing relay 301. Relay 301 upon energizing, locks through its inner left armature and front contact to the same ground. It will be remembered that relay 301 was not energized when connected in series with either resistance 716 or 770. When these two resistances in parallel are connected in the circuits of relay 301, it receives sufficient current to energize. A circuit is then completed from grounded battery, winding of the power magnet of sequence switch 200, upper right contact of sequence switch spring 201, conductor 247, inner right armature and front contact of relay 301, to ground on conductor 318 as previously traced, causing this sequence switch to be returned to position 1. Relay 301 also completes an obvious circuit for lamp 354, which

is illuminated as an indication that more than one master switch is off normal. Relay 301 also opens at its outer left armature and back contact the circuit for advancing sequence switch 200 out of position 1.

The master switch or switches which are inadvertently off normal, are restored to their normal positions by the alternate operation and release of the associated key 5 corresponding to key 759. The master switches are then stepped to their normal position in the manner previously described. When all but one of the master switches have been returned to normal, their associated "off-normal" relays corresponding to relay 760 deenergize. The circuit through the winding of relay 301 then extends to battery only through the inner left armature and front contact of relay 713. 10 As has been before mentioned, the current through relay 301 under this condition is insufficient to hold it energized. It therefore deenergizes, opening the circuit of lamp 354, which is extinguished, and at its 15 outer left armature and back contact re-establishing a circuit for advancing sequence switch 200 out of position 1 and into position 2.

When a spare terminal, that is one to 20 which no group switch is connected, is encountered on a master switch a circuit is established from grounded battery, brush arm 602 and its associated first terminal, conductor 606, operated contact of key 1, conductor 14, left contact of sequence switch spring 216, conductor 218, inner right armature and back contact of relay 313, conductor 314, brush arm 709 and the associated spare terminal, conductor 771 which is 25 multiplied to every spare terminal, winding of relay 358, to ground. Relay 358 is energized in this circuit and at its left armature and back contact opens the holding circuit for relays 501 and 502, causing 30 these relays to deenergize. At its right armature and back contact, it opens the circuit through relay 301. It also completes a circuit from grounded battery, winding, 35 armature and back contact of magnet 705, conductor 788 the spare terminal in the arc served by brush 708, conductor 334, intermediate right armature and back contact of relay 332, conductor 257, lower contact of sequence switch spring 229, conductor 361, 40 left armature and front contact of relay 358, conductor 304, upper contacts of sequence switch spring 601, to ground. Magnet 705 is energized and interrupts its own circuit, advancing the brush assembly of the 45 master switch to the next terminal.

The function of key 341 will now be explained. If the polarized supervisory relay in the district selector circuit under test should remain in its operated position after 50 being energized by the busy-back inter-

rupter in the course of regular service operation, a false charge may occur. In order to test for this condition, key 341 is operated at the beginning of the second revolution of sequence switch 200. It will 55 be remembered that when sequence switch 50 enters position 6 on the second revolution of sequence switch 200, relay 283 was energized. When sequence switch 200 reaches position 4 3/4 and relay 526 energizes as an 60 indication that the district is ready to be tested, a circuit is established from grounded battery, left armature and front contact of relay 283, conductor 206, winding of 65 relay 244, conductors 599 and 180, inner right armature and back contact of relay 160, conductor 181, operated contact of key 341, conductor 363, right armature and front contact of relay 526, conductors 527 and 528, upper left contact of sequence switch 70 spring 237, to ground. A circuit is also established from grounded battery, inner right armature and front contact of relay 283, conductor 498, winding of relay 576, conductor 599, to ground over conductor 80 75 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 When the contact of interrupter 296 opens, the district supervisory relay should deenergize. Should the supervisory relay fail to deenergize upon the opening of the contact of interrupter 296, the charge relays in the district circuit are energized falsely and relays 346 and 345 are energized, also falsely, in position 18 of sequence switch 200.

It will be noted that the circuit for advancing switch 200 out of position 14 on its second revolution is opened at the back contacts of relay 576. When relay 291 energizes in position 14, a circuit is closed from grounded battery, outer left armature and front contact of relay 291, conductor 278, outer left armature and front contact of relay 576, right windings of relays 577 and 583, conductor 519, inner right armature and back contact of relay 577, right armature and front contact of relay 576, contact of interrupter 574, conductor 37, lower right contact of sequence switch spring 64 to ground. Relay 583 is energized in this circuit but relay 577 does not receive sufficient current through its right winding to energize at this time. When interrupter 574 disengages its contacts, this circuit is opened and a circuit is then completed from ground, left armature and front contact of relay 583, left windings of relays 577 and 583 in parallel, right windings of relays 583 and 577 in series, outer left armature and front contact of relay 576 to battery on conductor 278. Relay 577 is energized and relay 583 is held energized in this circuit. Upon the next closure of interrupter 574, a circuit extends from battery on conductor 278, outer left armature and front contact of relay 576, through the right winding of relay 577, inner right armature and front contact of relay 577, right armature and front contact of relay 576, contact of interrupter 574 to ground on conductor 37. Relay 583 is shunted in this circuit and deenergizes, but the right winding of relay 577 receives sufficient current to hold the relay energized.

A circuit is closed from battery on conductor 278, winding, left armature and back contact of relay 279, conductor 580, inner left armature and front contact of relay 576, conductor 523, right armature and back contact of relay 583, outer left armature and front contact of relay 577, to ground for energizing relay 279. A circuit is now established from grounded battery on conductor 278, winding of relay 282, outer right armature and front contact of relay 279, conductor 284, contact of interrupter 575, conductor 37 to ground. Relay 282 is energized in this circuit. When interrupter 574 next disengages its contact, the circuit of relay 577 is opened and this relay deenergizes. Upon the next closure of the contact of interrupter 574, relay 583 is ener-

gized, in the manner described. Relay 577 is energized and relay 583 is held energized upon the opening of the contact of interrupter 574, and, upon its next closure, relay 583 is shunted and deenergized. A circuit is then established from grounded battery, winding of the power magnet of sequence switch 200, upper left contact of sequence switch spring 235, right armature and front contact of relay 291 and 282, inner right armature and front contact of relay 279, conductor 580, inner left armature and front contact of relay 576, conductor 523, left armature and back contact of relay 583, outer left armature and front contact of relay 577 to ground for advancing this sequence switch out of position 14 and into position 15. Sequence switch 200 is advanced out of position 15 and into position 18 over a circuit which may be traced from grounded battery, winding of the power magnet of sequence switch 200, lower right contact of sequence switch spring 234, conductors 156 and 158, upper left contact of sequence switch spring 59 to ground. The energization of relay 346 completes a circuit from grounded battery, windings of relays 331 and 342, inner right armature and back contact of relay 342, conductor 353, inner right armature and front contact of relay 244, conductor 298, left armature and back contact of relay 578, conductor 587, armature and front contact of relay 346, conductor 347, outer left armature and back contact of relay 157, conductor 155, lower contact of sequence switch spring 54 to ground. Relay 331 is energized in this circuit and locks through the winding of relay 342 and its own right armature and front contact to ground on conductor 363 when relay 346 is deenergized. This occurs, it will be remembered, when message register current is disconnected by the district circuit. The deenergization of relay 346 causes the energization of relay 342 over the circuit as above explained. Relay 342, upon energization, closes a circuit from grounded battery, lamp 355, left armature and front contact of relay 342, conductors 315 and 670, operated contact of key 15 to ground. Lamp 355 is illuminated as an indication that a false charge has been made. Relay 331 at its left armature and back contact, opens the circuit for advancing sequence switch 200 out of position 18. This circuit may be traced from grounded battery, winding of the power magnet of sequence switch 200, lower right contact of sequence switch spring 235, conductor 566, outer right armature and front contact of relay 244, conductor 362, left armature and back contact of relay 331, armatures and back contacts of relays 345 and 352 to ground.

If the supervisory relay in the district deenergizes when interrupter 296 opens its

contact, relay 346 does not energize and the sequence switch 200 is advanced to position 1, over the circuit just traced.

In case of false charge, the district selector circuit continues to revolve, preventing its being seized by a line switch. Sequence switch 200 is moved out of position 18 by the operation of key 2, which completes a circuit from grounded battery, winding of the power magnet of sequence switch 200, upper right contact of sequence switch spring 201, conductor 178, operated contact of key 2 to ground. When sequence switch 200 leaves position 18, relays 331 and 342 are deenergized, extinguishing lamp 355.

On coin type districts, sequence switch 50 is in position 15. The supervisory relay 1143 should energize and deenergize with the closing and opening of the contact of interrupter 296 over the circuit above traced. If the supervisory relay deenergizes properly, the sleeve relay 1102 is held energized, and negative coin battery is connected from the sender to the test circuit, causing the energization of relay 329. The energization of relay 329 in turn causes the energization of relay 560 in a circuit previously traced. Relay 564 is then energized as previously described and when coin battery is disconnected from the tip conductor, relays 329 and 560 are deenergized. The release of relay 560 completes a path from grounded battery, winding of the power magnet of sequence switch 200, lower right contact of sequence switch spring 235, conductor 566, right armature and front contact of relay 564, left armature and back contact of relay 560 to ground, for moving this sequence switch out of position 18 into position 1. If, however, the district supervisory relay does not deenergize, positive coin battery is connected, causing the energization of relay 340. The energization of relays 331 and 342 in a circuit from ground, upper right contact of sequence switch spring 56, conductor 343, armature and front contact of relay 340, conductor 587, left armature and back contact of relay 578, conductor 298, inner right armature and front contact of relay 244, conductor 353, inner right armature and back contact of relay 342, winding of relay 331 to grounded battery. The energization of relays 331 and 342 perform the same functions as described above for message rate districts.

A test may be made for the presence of a false ground on sleeve conductor of the two-partly district by the operation of key 341. When sequence switch 200 enters upon its third revolution preparatory to testing message rate registrations on the second party of a two party line, it will be remembered that sequence switch 50 ad-

vances from position 8 into position 9, that relays 115 and 116 are energized, that relays 103, 148, 101, 161, and 149 are also energized. A circuit may be traced from ground on conductor 105, inner right armature and front contact of relay 115, winding of relay 159, inner right armature and back contact of relay 157, conductor 166, outer left armature and front contact of relay 103, conductor 165, lower right contact of sequence switch spring 203 to grounded battery. Relay 159 energizes in this circuit and locks through the winding of relay 157 which in turn energizes through the armature and front contact of relay 159, conductor 168, lower contact of sequence switch spring 58 to grounded battery. A circuit is then closed from grounded battery, winding of relay 160, inner left armature and front contact of relay 157 to ground. The energization of relay 160 causes the deenergization of relay 244. When sequence switch 200 enters position 10, relay 266, it will be remembered, energizes, in turn causing the energization of relay 269. A circuit may then be traced from grounded battery, winding of relay 260, left armature and front contact of relay 269, conductor 170, inner left armature and front contact of relay 160, conductor 171, lower left contact of sequence switch spring 59 to ground for energizing relay 260.

With sequence switch 1000 in position 11 to which it has been rotated by the action of sender 1010 as explained in the Stearn et al. patent, a circuit is closed from grounded battery through the right winding of relay 1065, terminal 3 of the arc served by brush 1066, conductor 1067, lower left contact of sequence switch spring 1053, upper left contact of sequence switch spring 1056, to ground for energizing relay 1065. When brush 1042 rotated to terminal 14, as explained in the above mentioned patent, a circuit may be traced from grounded battery, winding of relay 1064, terminal 14 in the arc served by brush 1042, upper left contact of sequence switch spring 1009, conductor 839, brush 814 and its associated contact, conductor 779, brush arm 752 and its associated contact, conductor 742, outermost right armature and back contact of relay 332, conductor 333, lower left contact of sequence switch spring 225, armature and front contact of relay 260, conductor 588, winding of relay 350, conductors 589 and 170, inner left armature and front contact of relay 160, conductor 171, lower left contact of sequence switch spring 59 to ground. Relays 350 and 1064 are energized in this circuit. The energization of relay 1064 completes a circuit from grounded battery, right winding of relay 1068, right armature and

front contact of relay 1065, armature and front contact of relay 1064 to ground. Relay 1068 is energized.

The district selector circuit now prepares 5 to send out message register current on the second party sleeve conductor 838, in the manner previously described. When sequence switch 200 leaves position 10 it opens the circuit through relays 1064 and 10 350 deenergizing these relays and when sequence switch 200 reaches position 14, a circuit is closed from grounded battery, upper left contact of sequence switch spring 203, conductor 217, winding of relay 349, conductor 311, inner right armature and front contact of relay 160, conductor 181, operated contact of key 341, conductor 363, right armature and front contact of relay 526, conductors 527 and 528, upper left contact of sequence switch spring 237 to ground for energizing relay 349. Relay 578 is now energized in a circuit which may be traced from grounded battery, windings of relay 578, conductor 525, inner left armature and front contact of relay 349 to ground.

When sequence switch 1000 controlling the district selector circuit reaches position 17 and with sequence switch 200 in position 36 18, a circuit extends from ground at the lower left contact of sequence switch spring 59, conductor 171, inner left armature and front contact of relay 160, conductors 170 and 589, winding of relay 350, inner right armature and front contact of relay 349, conductor 322, outer right armature and back contact of relay 584, conductor 297, lower right contact of sequence switch spring 225, conductor 333, outermost right armature and back contact of relay 332, conductor 742, brush arm 752 and its associated contact, conductor 779, brush arm 814 and its associated contact, conductor 839, as traced through the winding of the district 40 relay 1064 energizing relay 1064 and relay 350. The energization of the district relay prevents the party selector switch from moving to terminal 17. A circuit is now established from ground at the lower left contact of sequence switch spring 209, conductor 359, left winding of relay 348, left armature and front contact of relay 350 to grounded battery causing the energization of relay 348 which locks through its right winding, inner right armature and front contact to battery at the outer left armature and front contact of relay 349. The energization of relay 348 establishes a circuit from grounded battery, inner right armature and front contact of relay 578, conductor 529, winding, left armature and back contact of relay 585, conductor 540, outer right armature and front contact of relay 578, contact of interrupter 579, conductor

319, outer left armature and front contact of relay 348, conductor 525, inner left armature and front contact of relay 349 to ground. Relay 585 is energized in this circuit and locks to ground on its own left armature and front contact. A circuit is then completed from grounded battery, winding of relay 584, right armature and front contact of relay 585, conductor 499, contact of interrupter 581 to ground on conductor 319 for energizing relay 584. The circuit through the winding of relay 350 is opened at the outer right armature and back contact of relay 584, and a shunt circuit is placed around the left winding of relay 578 causing this relay to deenergize. The advance of 80 the district circuit in the well known manner now causes the energization of relays 351 and 352 over conductor 838 as previously explained and a circuit is established from grounded battery, winding of relay 560, conductors 561 and 562, inner left armature and back contact of relay 244, conductor 298, left armature and back contact of relay 578, conductor 587, armature and front contact of relay 351, outer right armature and front contact of relay 349, conductor 172, outer left armature and front contact of relay 157, conductor 155, lower left contact of sequence switch spring 54 to ground. Relay 560 is energized in this circuit causing in turn the energization of relay 564 in a circuit which may be traced from grounded battery, right armature and front contact of relay 560, winding of relay 564, conductor 565, lower left and upper right contacts of sequence switch spring 222 to ground. Relay 564 locks through its left armature and front contact to battery. The district selector circuit now advances in the well known manner causing the deenergization of relay 351 which in turn causes the deenergization of relay 560. A circuit may now be traced from grounded battery, winding of the power magnet of sequence switch 200, lower right contact of sequence switch spring 235, conductor 566, right armature and front contact of relay 564, left armature and back contact of relay 560 to ground for advancing this sequence switch into position 1. 105 110 115

What is claimed is:

1. In a telephone exchange system, a testing device for testing switches, said switches to be tested having different characteristics and being grouped according to their respective characteristics, means for connecting said testing device with any group of said switches, and means for determining the character of the switches of said group. 120
2. In a telephone exchange system, a testing device for testing switches, said switches having different characteristics and being grouped according to their respective char- 125

- acteristics, means for connecting said testing device to the groups of switches successively, and means for determining the character of the switches of said groups.
- 5 3. In a telephone exchange system, a testing device for testing switches, the switches to be tested having different characteristics and being grouped according to their respective characteristics, means for connecting said testing device with any one of said switches, means at said testing device for applying characteristic tests to the switches of different character, and means associated with said testing device for altering the circuits thereof for applying the proper tests in accordance with the character of the particular switch selected.
- 10 4. In a telephone exchange system, a testing device for testing switches, the switches to be tested having different characteristics and being grouped according to their respective characteristics, means for connecting said testing device with each of said switches successively, means at said testing device for applying characteristic tests to the switches of different character, and means associated with said testing device for altering the circuits thereof for applying the proper tests in accordance with the character of the switch under test.
- 15 5. In a telephone exchange system, a testing device for testing switches, means for successively selecting switches to be tested and for connecting them with said testing device, the switches to be tested being at the time of selection either idle, busy in service connections, artificially busy or in reserve, and means in said testing device for indicating the condition of each switch upon its association with said testing device.
- 20 6. In a telephone exchange system, a testing device for testing switches, means for selecting a particular switch to be tested, said switch being at the time of selection either idle, busy in service connection, artificially busy, or in reserve, and means for determining in which of these conditions said switch is found upon its selection by said testing device.
- 25 7. In a telephone exchange system in which selector switches are controlled in their selective movements by a common central office register sender and in which impulses are transmitted over paths associated with said switches to said sender, a testing device, comprising automatic means for successively selecting switches to be tested and for connecting them with said testing device, means to actuate each selected switch to cause the association of a sender therewith and the establishment of said impulse transmitting paths, and means for testing the condition of said impulse transmitting path through each switch under test.
- 30 8. In a telephone exchange system in which selector switches are controlled in their selective movements by a common central office register sender and in which impulses are transmitted over paths associated with said switches to said sender, a testing device comprising automatic means for selecting a particular switch to be tested and for connecting it with said testing device, means to actuate said switch to cause the association of a sender therewith and the establishment of said impulse transmitting paths, and means for testing the continuity of said associated path.
- 35 9. In a telephone exchange system in which selector switches are controlled in their selective movements by a common register sender and in which a dialing tone is transmitted from the center to the calling lines over paths associated with said switches, a testing device, comprising automatic means for successively selecting switches to be tested and for connecting them with said testing device, means to actuate each selected switch to cause the association of a sender therewith and the establishment of said tone paths, and means for testing the condition of the tone path through each switch under test.
- 40 10. In a telephone exchange system in which selector switches are controlled in their selective movements by a common register sender and in which a dialing tone is transmitted from the sender to the calling lines over paths associated with said switches, a testing device, comprising automatic means for selecting a particular one of said switches and for connecting it with said testing device, means to actuate said switch to cause the association of a sender therewith and the establishment of said tone path, and means for testing the continuity of said path.
- 45 11. In a telephone exchange system in which selector switches are employed for extending connections, each switch having a supervisory relay operated from a subscriber's line, a testing device comprising automatic means for successively selecting switches to be tested and for connecting them with said testing device, means for positioning a selected switch to associate said supervisory relay with said testing device, means in said testing device for automatically and successively applying testing current of different values to the relay of each switch under test, and means for indicating the response of said relay to said testing current.
- 50 12. In a telephone exchange system in which selector switches are employed for extending connections, each switch having a supervisory relay operated from a subscriber's line, a testing device, comprising auto-

matic means for selecting a particular switch to be tested and for connecting it with said testing device, means for positioning said switch to associate said supervisory relay with said testing device, means for automatically and successively applying testing current of different values to the relay of said switch under test, and means for indicating the response of said relay to said testing current.

13. In a telephone exchange system in which selector switches are employed for extending connections, each switch having a call charging relay responsive to the successful completion of a connection over said switch to a wanted line, a testing device, comprising automatic means for successively selecting switches to be tested and for connecting them with said testing device, means for positioning a selected switch to associate said relay with said testing device, means for automatically and successively applying testing current of different values to the relay of each switch under test, and means for indicating the response of said relay to said testing current.

14. In a telephone exchange system in which selector switches are employed for extending connections, each switch having a call charging relay responsive to the successful completion of a connection over said switch to a wanted line, a testing device comprising automatic means for selecting a particular switch for test and for connecting it with said testing device, means for positioning said switch to associate said relay with said testing device, means for automatically and successively applying testing current of different values to the relay of said switch under test, and means for indicating the response of said relay to said testing current.

15. In a telephone exchange system in which selector switches are employed for extending connections, a testing device, automatic means for successively extending connection from said testing device to selector switches to be tested, means in said testing device for automatically and successively applying different tests to parts of the switch under test, and means for repeatedly applying said tests to a switch under test.

16. In a telephone exchange system in which selector switches are employed for extending connections, a testing device, automatic means for extending a connection from said testing device to any selector switch which it is desired to test, means in said testing device for automatically and successively applying different tests to parts of the switch under test, and means for repeatedly applying said tests to a switch under test.

17. In a telephone exchange system in

which a selector switch is employed for extending connections and in which the talking path through the switch is altered in accordance with the character of the connection established thereover, a testing device, means for extending a connection from said testing device to said switch, means in said testing device for successively controlling the setting of said switch into positions in which said several talking paths are established and means for testing said talking paths.

18. In a telephone exchange system in which the selector switch is set under the control of a central office sender and in which the talking path through said switch is altered under the control of the sender in accordance with the character of the connection established thereover, a testing device, means for extending a connection from said testing device or said switch, means in said testing device for successively setting the registers of said sender for advancing said switch into positions in which said several talking paths are established, and means for testing said talking paths.

19. In a telephone exchange system in which selector switches are employed for extending connections, a testing device comprising automatic means for successively extending connections from said testing device to selector switches to be tested, means for actuating each of said switches to take a plurality of different settings, and means for applying a plurality of tests to each switch during each of said settings.

20. In a telephone exchange system in which selector switches are employed for extending connections, a testing device comprising automatic means for extending a connection from said testing device to any selector switch which it is desired to test, means for actuating said switch to take a plurality of different settings and means for applying a plurality of tests to said switch during each said setting.

21. In a telephone exchange system in which selector switches are employed for extending connections, each switch having a plurality of supervisory relays, a testing device comprising automatic means for successively selecting switches to be tested and for connecting them with said testing device, means for positioning a selected switch to associate each of said relays with said testing device in turn, means for successively applying test current of different values to the associated supervisory relay, and means for indicating the response of each relay to said test current.

22. In a telephone exchange system in which selector switches are employed for extending connections, each switch having a plurality of supervisory relays, a testing

device comprising automatic means for selecting the particular switch to be tested and for connecting it with said testing device, means for positioning said switch to associate each of said relays with said testing device in turn, means for successively applying test current of different values to the associated supervisory relay, and means for

indicating the response of said relay to said testing current.

In witness whereof, we hereunto subscribe our names this 6th day of December A. D., 1923.

ARNOLD S. BERTELS.
EDWIN F. TRAPP.
